UNITED STATES PATENT OFFICE

2,031,479

SHOE SEWING MACHINE

Otto R. Haas, North Beverly, Mass., assignor to
 United Shoe Machinery Corporation, Paterson,
 N. J., a corporation of New Jersey.

Application March 19, 1932, Serial No. 600,016

86 Claims. (Cl. 112—37)

The present invention relates to shoe machines and is herein set forth as embodied in an outsole stitcher of the type in which the shoe and the stitch forming devices are moved relatively to transfer the point of operation about the shoe and to change the relative positions of the shoe and the operating means to present the shoe properly to the operating means as the point of operation is transferred about the shoe, and in which the shoe is supported in operating position in the machine and all of its movements are effected and controlled by automatically acting mechanisms.

The primary object of the present invention is to improve the construction and mode of operation of automatic outsole shoe sewing machines and to produce a machine of this type which is more efficient, reliable and uniform in its operation than prior machines and upon which an operation on a shoe may be successfully performed by a comparatively unskilled operator with a minimum expenditure of labor and time. Certain features of the invention may be utilized to advantage in connection with shoe sewing machines other than outsole stitchers or in connection with machines for performing other shoe making operations. Also, certain features are not limited to use in machines which are wholly automatic in character, but may be embodied in machines in which at least some of the required relative movements of the operating instrumentalities and shoe are produced or controlled by the operator.

In operating prior automatic shoe machines considerable manual effort has been required to set the machine in operation due to the frictional resistance of the starting mechanism, to the necessary mass of the manipulated parts and to the number of different operations performed simultaneously or in timed relation to the coupling of the rotating parts to the power driver.

An important feature of the present invention, therefore, contemplates the provision of a manually controlled power driven starting apparatus for coupling a shoe machine to a power driving member to relieve the operator of the physical exertion which would otherwise be required and to insure uniform and certain actuation of the coupling parts in suitable timed relation to any secondary operations that may be required or considered desirable. In the machine hereinafter described this feature of the invention is embodied in a construction comprising a power driving member, a main driven member, a main clutch for coupling the driving member to

the driven member, an auxiliary shaft, an auxiliary clutch for coupling the auxiliary shaft for actuating the main clutch, and a manual control for causing the engagement of the auxiliary clutch. In the construction hereinafter described, this auxiliary shaft, in addition to causing the actuation of the main clutch is also utilized for performing certain preliminary operations to place the various parts of the machine in proper position to act on the shoe when the machine is started. The machine hereinafter described in which the several features of the present invention have been embodied is an automatic outsole stitcher and, in this machine, the preliminary operations performed by the auxiliary shaft during or prior to the throwing in of the main clutch consist in locking a portion of the jack actuating mechanism which has been adjusted in accordance with the size of the shoe by the movement of the shoe into the machine in adjusting a portion of the driving mechanism for operation on the size of shoe which is in the jack, in resetting the looper mechanism, which has been rendered inoperative at the conclusion of the sewing operation on the preceding shoe, in releasing the presser-foot to allow it to clamp the work and in rotating the tension wheel to supply an amount of thread to the stitch-forming devices which will insure the proper formation of the initial stitches of the seam.

An automatic shoe machine of the type in which the features of the present invention have been embodied is constructed and arranged to perform several auxiliary operations after the completion of the main operation on the shoe. These operations include moving the jack outwardly away from the operating devices and returning it to initial position and, in the case of a sewing machine, also include severing the thread and relatively moving the work clamping devices to release the shoe. To enable these auxiliary operations to be performed in the proper sequence and in an efficient and reliable manner, a feature of the present invention contemplates the provision of a plurality of power driven auxiliary mechanisms which are rendered operative at the conclusion of the main operation and each of which comprises an auxiliary clutch for coupling the mechanism to a main power driver. By employing a plurality of auxiliary power driven mechanisms, each operation can be performed at the desired speed and in proper timed relation to the operating parts of the machine and the auxiliary clutches for coupling the mechanisms to the main driver may be controlled and actuated

from those parts of the machine best adapted to produce the desired results. Thus, in the case of the thread cutter and shoe clamping presser-foot of the machine hereinafter described, the corresponding auxiliary clutch is controlled from the sewing cam shaft and thereby the proper actuation of the thread cutter and presser-foot is timed in relation to the stitch-forming devices is insured.

10 The stitch-forming devices of the machine hereinafter described are so timed that the awl enters the work after the needle has withdrawn with its loop of thread and before the loop has been drawn into its final position in the seam to set the stitch. Machines having stitch-forming devices timed in this manner have heretofore been devised, examples of such machines being disclosed in U. S. patent to Laurence E. Topham, No. 1,462,587, dated July 4, 1923, and in the application of Laurence E. Topham, Serial No. 265,-169, filed March 27, 1928 upon which Patent No. 1,905,074 issued April 25, 1933. In order to stop these machines at the completion of the sewing with the stitch completed and with both the 25 needle and awl out of the work, it is necessary to turn the machine backwards, after the last needle loop has been drawn down into the work by the take-up, to a point in the stitch-forming cycle at which, during the normal operation of 30 the machine, the awl is about to enter the work, as otherwise upon starting the machine the needle will at once enter the work and be liable to become bent or broken by reason of the fact that no awl hole has been made in the work to receive it. If, at the completion of the sewing, these machines are stopped at the point in a forward cycle of the stitch-forming devices at which the awl is about to enter the work, the last stitch will not be completed, and the needle loop will be 35 retained in the barb of the needle, thereby interfering with the withdrawal of the work from the machine. A feature of the present invention is embodied in a construction for bringing the stitch-forming devices to rest at the completion 40 of the sewing with the stitch completed and with the awl in a position to enter the work and without imparting a reverse movement to said devices. This feature of the invention contemplates securing this result in any suitable manner. In 45 the construction hereinafter described, this feature is embodied in a stop mechanism which acts to stop the stitch-forming devices at that point in the cycle where, during the normal operation of the machine, the needle has withdrawn from 50 the work with a loop of thread in its hook, in combination with a mechanism acting during the final work-piercing stroke of the needle to prevent the thread from being placed in the hook of the needle so that the needle finally comes 55 to rest without any loop of thread in its hook.

Other features of the present invention embodied in the machine hereinafter described are a novel and improved looper mechanism for threading the needle, a novel and improved construction by which the looper is prevented from threading the needle upon stopping the machine, an improved manner of operating the looper so as to support the needle while the needle is in the work and during the relative work feeding 60 parts, a new and improved mechanism for handling the thread and particularly the bobbin or locking thread, a novel and improved means for severing the thread at the completion of the sewing operation, and a novel and improved mech-

anism for supporting and actuating an edge gage and so-called fudge knife for cutting a stitch receiving groove in the welt.

The features of invention above referred to and other novel constructions, combinations and arrangements of parts hereinafter described and claimed will be readily understood by those skilled in the art from the following description taken in connection with the accompanying drawings which illustrate an automatic outsole 10 stitcher constituting one specific embodiment of the several features of the invention.

In the drawings Figure 1 is a view in front elevation of the complete machine with the lower portion of the main base broken away to show the underlying parts and the motor and certain other parts broken off at the top; Figure 2 is a view in side elevation of the machine looking from the left of Figure 1 with a portion of the casing or frame of the base broken away 15 and shown in section; Figure 3 is a plan view of the machine with the frames for the power drive and sewing mechanism removed, and with the base partly broken away to show the construction and mechanism within the base; Figure 4 is a sectional plan view of the machine on a plane passing just below the top of the base, parts having been removed to simplify illustration; Figure 5 is a plan view, partially in section on an enlarged scale showing the mechanism 20 below the motor and parts of the sewing mechanism; Figure 6 is a view in elevation of the upper portion of the machine from the right side, partly in section, illustrating particularly the driving mechanism; Figure 7 is a view in 25 front elevation, partly in section of an upper portion of the machine; Figure 8 is a view similar to Figure 6, parts having been broken away and shown in section along a plane passing through the machine nearer to the right side; Figures 9 and 10 are sectional views in side elevation of a portion of the jack supporting and actuating mechanisms in different positions on the same scale as Figure 2; Figure 11 is a plan view, partly in section, on an enlarged scale of 30 the right forward portion of the main case of the machine; Figure 12 is a side sectional view taken along the lines 12-12 of Figure 11; Figure 13 illustrates diagrammatically a wiring system for electrically connecting various parts of 35 the machine; Figure 14 is a detail plan view of a lost motion switch; Figure 15 is a sectional view in front elevation of the switch indicated in Figure 14; Figure 16 is a view in front elevation of the sewing mechanism of the machine, 40 with parts of the casing broken away; Figure 17 is a view in side elevation of the mechanism shown in Figure 16, parts of the casing having been broken back to illustrate more clearly the underlying parts; Figure 18 is a similar view on an enlarged scale, certain of the parts having been removed; Figure 19 is an enlarged sectional view taken along lines 19-19 of Figure 18; Figure 20 is a view in side elevation, partly in section, of a portion of the sewing mechanism; Figure 21 is a plan view of the sewing mechanism, parts of the casing having been removed and shown in section to expose the operating members; Figure 22 is a sectional view on an enlarged scale showing certain parts of the 45 thread break indicating apparatus; Figure 23 is a view, partly in section, of the sewing mechanism taken from the left side of the machine; Figure 24 is a fragmentary view in vertical section illustrating a detail of an adjustment for 50

the feeding mechanism; Figure 25 is a view on an enlarged scale of a portion of the sewing mechanism from the left side of the machine; Figure 26 is a similar view from the right side of the machine; Figure 27 is a detail vertical sectional view of the locking thread mechanism shown in Figure 26, taken in a plane indicated by the line 27-27 of Figure 28; Figure 28 is an enlarged view along the line 28-28 of Fig. 26; Figure 29 is a similar view along the line 29-29 of Figure 26; Figure 30 is a view in rear elevation of a portion of the sewing mechanism and its supporting frame; Figure 31 is a view in elevation, partly in section, on an enlarged scale of the thread tension devices; Figure 32 is a side view in section taken along the line 32-32 of Figure 31; Figure 33 is another side sectional view along the line 33-33 of Figure 31; Figure 34 is a plan view in partial section illustrating on an enlarged scale a portion of the mechanism shown in Figure 5; Figure 35 is a view in front sectional elevation of a part of the stitch forming devices; Figure 36 is a detail view of the locking thread measuring member in partial side section; Figure 37 is a view in front elevation of the thread measuring member shown in Figure 36, showing its relation to the work; Figure 38 is a detail view in partial section of the needle and awl carrying stud and lateral feed nut taken along the line 38-38 of Figure 39; Figure 39 is a sectional view of the same parts taken along the line 39-39 of Figure 38; Figure 40 is a detail view showing, in side elevation and section, certain of the parts illustrated in Figure 8; Figure 41 is a detail sectional view taken on the line 41-41 of Figure 40; Figure 42 is a detail sectional plan view illustrating particularly the feed carriage and the looper mechanism; and Figure 43 is a detail sectional plan view of a portion of the looper mechanism.

Referring to Figures 1, 2, and 3 of the drawings, the frame of the machine comprises a main base 2 having a horizontal top 4. Suspended through an opening in the top is a cradle 6, machined to carry the frames 8 and 10 for the power drive and the sewing mechanism, respectively. The power drive frame 8 supports a casting 12 carrying the power starting mechanism, and a driving motor 14 is attached to a flange 50 at the top of the power starting casting.

The motor 14 is mounted to drive a vertical shaft 16 (see Figs. 5, 6, and 8) for operating the constantly rotating main power driver, indicated by the reference numeral 18. The upper end of shaft 16 is supported within the motor and the lower end, by a bearing 20 carried by a sleeve 22 formed in the power starting casting 12. The connection between the motor shaft 16 and the power driver 18 comprises a spur gear 24 fixed 60 to the motor shaft 16 which meshes with and drives an idler gear 26 mounted to rotate on a fixed shaft and meshing with an internal gear 28 formed on the power driver 18. The power driver is continuously rotated by the motor and is pinned to the upper end of a vertical shaft 30 held in alignment by a radial bearing 32 with the end of the motor shaft 16.

The power driver 18 is formed at its lower portion with a conical clutching surface 34 for engaging a correspondingly shaped internal clutching surface 36 on a driven clutch member 38. The clutch member 38 extends upwardly from a sleeve 40 freely slidable and rotatable on the shaft 30 and having an integrally formed helical gear 42 at its central portion for driving the

sewing cam shaft and the pattern cam shaft of the machine. The driven clutch member 38 is held in engagement with the clutching surface of the power driver by a heavy compression spring 44 bearing at one end on the sleeve 40 and at the other on a thrust bearing carried by the power drive frame. The outside surface of the driven clutch member is also conical in shape and is adapted to engage an annular braking member 46 attached to the frame.

Means are provided for disengaging the driven clutch member from the main driver at the proper time and wedging it within the braking member 46 to arrest the movement of the helical gear 42 and the sewing cam shaft and pattern cam shaft 15 driven thereby. These means are substantially the same as in the driving and stopping mechanism described in the U. S. patent to Topham No. 1,791,176 granted February 3, 1931, and comprise a suitably shaped cam slot 48 formed in 20 the sleeve 40 for engagement with a lock bolt 50. The lock bolt is mounted in a carrier 52 rigidly secured to a horizontal rock shaft 54 mounted in the frame of the power drive. The lock bolt 50 is mounted to slide in an arm of the bolt carrier and is urged toward the cam slot 48 by a spring 56 (see Fig. 7).

While the machine is in operation and while the sewing and pattern cam shafts are being driven, the lock bolt 50 is out of engagement with the cam slot 48 and the clutch member 38 is held in engagement with the power driver 18 by the force exerted by the spring 44 on the sleeve 40. To disengage the driven clutch member from the power driver, the lock bolt is allowed 35 to engage the cam slot 48 in the sleeve 40 and at a certain point in the revolution of the sleeve the carrier for the bolt is held against movement, thereby causing the lock bolt and cam groove to cooperate in forcing the sleeve 40 with the clutch member 38 away from the power driver against the force of the spring 44, and bringing the brake surface on the driven clutch member into engagement with the fixed braking member 46. While the clutch members are in engagement, the horizontal arm of the carrier in which the bolt is mounted is maintained in raised position by a spring 57 stretched between the vertical arm of the carrier and the frame of the machine. When the locking bolt is allowed to move toward the cam slot, it engages the outer surface of the sleeve 40 and slides into the slot when the slot registers with the bolt. Continued rotation of the sleeve causes the locking bolt to be moved downwardly and the lock bolt carrier to be moved in a clockwise direction. Movement of the lock bolt carrier in a counter-clockwise direction and movement of the locking bolt in an upward direction is then prevented by the engagement of the vertical arm of the lock bolt carrier by a spring pressed latch 58. The lock bolt carrier with the lock bolt 50 is thus held against movement and the continued rotation of the sleeve 40 causes the separation of the clutch members by the cooperative action of the cam slot 48 and the stationarily held lock bolt 50.

Outsole shoe sewing machines of the character herein described are heavily constructed and of considerable mass, requiring a heavy braking force to be applied in stopping at a definite point. 70 This force is at a maximum with the parts in a stopped position and produces a large amount of frictional resistance to the releasing movement of the latch 58 from engagement with the bolt carrier. To relieve the operator from the 75

exertion necessary to overcome this resistance, starting mechanism is provided in the illustrated machine to supply an unlimited amount of power for application in releasing the latch. This mechanism comprises a helical gear 62 (see Figs. 5 and 6) on the power driver 18 engaging with a gear 64 formed on a sleeve 66 rotating freely on a horizontal crank shaft 68 journaled in the power starting casing, from which shaft through connections, hereinafter described, the latch 58 is actuated to release the lock bolt carrier and the lock bolt is withdrawn from the cam slot 48. Beside the gear 64 on the sleeve 66 there is a spur gear 70 meshed with a gear 72 rotatable on a horizontal counter-shaft 74, also having bearings in the casting 12. The gear 72 is formed with a conical opening at one side and a correspondingly shaped hub member 76 fixed to the counter-shaft 74 enters into frictional engagement with the inner surface of gear 72. At the opposite side of the gear, a thrust bearing 78 reacts against a compression spring 80, to prevent slippage between the hub member and the gear 72. The outer end of spring 80 is backed by an adjustable collar 82 threaded onto the shaft 74. At the end of the counter-shaft opposite from the gear 72, is fixed a spur gear 84 meshing with a gear 86 mounted loosely on the crank shaft 68 and comprising the driving part 30 of an auxiliary Horton or other one-revolution clutch. The driven part 88 of the clutch is keyed to a collar 90 fixed on the crank shaft 68. The gear 86 is continuously rotated by the train of gears, thus described, including the helical gear 62 on the main driver, gears 64 and 70 on the crank shaft 68, gear 72 rotating with the counter-shaft 74, and gear 84 meshing with gear 86.

The one revolution clutch is held in uncoupled condition by a slidable abutment 92 (see Figs. 5 and 8) carried on a rod 94 extending from a bell crank 96 pivoted to the power starting casting 12 by a screw 98. The abutment 92 is yieldingly maintained in position by a spring 100 for absorbing the shock which results from the stopping action of a projection 102 from the control disk 103 of the clutch. Pivoted mounted on the bell crank 96 is a pawl member 104 engaging with ratchet teeth 106, on the driven part 88 of the clutch. This pawl aids in maintaining the clutch in released condition by preventing reverse rotation of the driven parts. The pawl is resiliently maintained in contact with the ratchet teeth by a spring 108 tensed between the forward end of the pawl and the bell crank.

To enable the crank shaft to be operated, the constantly rotating gear 86 is coupled with the driven part 88 of the one-revolution clutch by rocking the bell crank 96 about its pivot screw 98, thereby moving the slidable abutment 92 out of contact with the projection 102 on the control disk of the clutch and connecting the driving gear 86 with the crank shaft 68 through one complete revolution. The bell crank 96 is rocked by means of a manually operated handle 110 pivoted at 112 on the power starting frame, the lower end being thrust outwardly by a compression spring 114 acting between the upper end of the handle and the frame. To prevent more than one revolution of the crank shaft for a single actuation of the manually operated handle 110, a latch 116 is pivotally mounted on the handle and extends into contact with a projection 118 on the lower arm of the bell crank 96. A spring 120 extends between the handle 110 and the latch 116 to force it downwardly and hold it

in a substantially horizontal position with a shoulder on the latch in engagement with the side of the handle. Manual operation of the handle 110 thrusts the latch 116 endwise against the projection 118 to rock the bell crank and release the projection on the clutch from the abutment 92. To prevent the crank shaft 68 from making more than one revolution, the driven part 88 of the clutch carries a cam 122 and, upon rotation of the crank shaft, the cam engages a roller 124 attached to the end of a release trigger 126 fulcrumed loosely at its central part on the counter-shaft 74. As the roller 124 is thrust downwardly by the cam 122, the other end 130 of the trigger rises to strike the latch 116 near its free end and lifts it from engagement with the projection 118 on the bell crank. As soon as the projection 118 is cleared by the latch 116, the abutment 92 falls into the path of the projection 102 under the action of a spring 132 compressed between the horizontal arm of the bell crank and the casting frame. As the crank shaft continues to rotate, the projection 102 strikes abutment 92 and the auxiliary clutch is again uncoupled.

Rotation of the crank shaft actuates the clutch bolt 59 and the carrier latch 58 to free the main driven clutch member 38 from engagement with the stationary brake and allow it to rise under the pressure of the compression spring, into driving relation with the power driver 18. For this purpose, the crank shaft 68 is provided with a crank 134 which actuates a vertical pitman 136 connected at its lower end with a vertical slide 138 (see Figs. 7 and 8). At an intermediate part of the pitman there are provided an opening and a lug carrying a vertically adjustable stop screw 140. The latch 58 is released from the lock bolt carrier and the clutch bolt 59 is withdrawn from engagement with the cam slot 48 by the action of the stop screw 140 through connections which are substantially the same as disclosed in Patent No. 1,791,176 and which comprise a pair of fingers 142 rotatable with a shaft 144 journaled in the frame of the machine. These fingers thrust against a collar 143 at the end of the clutch bolt to withdraw it. The shaft 144 is rotated by an arm 146 fixed to one end of the shaft and connected at its outer end to a link 148. The lower end of the link is pivotally connected by screw 150 to a horizontal lever 152 pivoted at 154 to the frame of the machine, the extending end of which lever is fashioned with a handle portion to provide for manual actuation, and is connected by an upwardly extending spring 156 for maintaining it in raised position so that the fingers 142 will not normally engage the collar at the end of the clutch bolt 59. The link 148 also carries a clamp block 158 adjustable longitudinally of the link. This clamp block is adjusted to release the latch 58 from the bolt carrier by striking a pair of fingers extending from the latch, which project at either side of the link 148. The screw 150 is formed with an elongated head portion to enter the slot in the pitman 136 and as the pitman descends during rotation of the crank shaft, stop screw 140 strikes the head of screw 150 (see Fig. 8), causing a release of the latch 58 from the bolt carrier and a withdrawal of the bolt 59 from engagement with the cam slot 48 in the driven clutch member 38. As soon as the driven clutch member is released, it moves upwardly under the action of the compression spring 44 into driving relation with the main driver 18 to set the machine in operation.

The fingers 142 are retained in clutch releasing position by a pivoted latch 160 acting against a projection 162 on one of the fingers. A spring is stretched between the latch and the frame of the machine to hold the latch 160 in engagement with the projection on the finger. 5

Manual operation of the handle 110 causes a single rotation of the crank shaft 68 and a reciprocation of the pitman 136 to move link 148 downwardly to release the main driven clutch member and start the machine. If the parts become so tightly wedged that breakage is imminent, gear 72 runs idly on the counter-shaft 74, exerting only the turning force provided by the frictional engagement with the conical hub member 76. 10

The sewing mechanism and the jack actuating mechanisms are driven by the driven clutch member 38 through two separate transmission systems as in the machine disclosed in the patent to Morrill No. 1,834,471, dated December 1, 1931. In the present construction, however, the helical gear 168 which meshes with the gear 42 formed on the sleeve 40 of the driving clutch member is mounted to rotate freely on the main horizontal sewing cam shaft 166 and is detachably connected to the shaft by means of a clutch member 170 mounted to rotate with and slide longitudinally on the shaft and provided with clutch projections engaging cooperating projections on the face of the gear 168. The clutch member 170 may be moved out of engagement with the gear 168 by means of a clutch shifting member 172 fulcrumed to swing about the pivot 154 on which the lever 152 is mounted, and connected by a short horizontal link 174 with an eccentric pin on the pivot of a hand lever 178. 15

The jack actuating mechanisms are driven from the gear 42 on the driven clutch member through a vertical shaft 180 (see Figs. 6 and 8) carrying a helical gear 182 at its upper end, meshing with the gear 42 and terminating in a slotted enlargement 183 at its lower end. Below the end of the enlargement, a serrated clutch block 184 is arranged with a key slidable in a slot axially of the shaft. Springs maintain the block in a lowered position against the upper toothed surface of an enlarged upper end 186 of a short vertical shaft 188 (see Figs. 8 and 12). Surrounding the shaft 188 is a sleeve 190 which is driven from the shaft 188 through a variable speed mechanism and which has attached at its lower end a pinion 192, this driving mechanism as so far described being the same as in the machine of Patent No. 1,834,471. From the pinion 192 (see Figs. 8, 11 and 12) the pattern cam shaft for controlling the position of the jack is driven through a train of gears comprising a gear 194 meshing with the pinion 192, an overrunning clutch 196 contained within the gear, a sleeve 198 on which the gear is supported and to which one member of the clutch is keyed, a gear 200 keyed at the lower end of the sleeve, a gear 202 meshing with the gear 200 and secured to the lower end of a short vertical shaft 204, an elongated pinion 206 fast on the shaft 204, a gear 208 meshing with the pinion 206 and a series of similar gears 210 secured together and to the gear 208, arranged to mesh with a gear 212 at the upper end of the pattern cam shaft. The pattern cam shaft is thus driven continuously so long as the driven clutch member 38 engages the main driver 18, the speed of rotation depending on the adjustment of the variable speed mechanism between the shaft 188 and the surrounding sleeve 190. This variable speed mechanism, as in 20

the machine of Patent No. 1,834,471, comprises a ratchet wheel 214 fast upon the shaft 188, a series of pawl carriers 216 pivotally mounted on the upper end of sleeve 190, a pawl 218 mounted on each pawl carrier and spring pressed into engagement with the ratchet 214 and an adjustable cam plate 220 (see Fig. 3) provided with a cam groove, engaging pins 222 projecting upwardly from the pawl carriers. 25

The pattern cam shaft indicated at 224 (see Figs. 1, 2 and 4) is illustrated as being provided with a single set of cams but may be provided with a series of sets as in the machine described in Patent No. 1,834,471. These cams may be brought into cooperative relation with the cam levers by a longitudinal adjustment of the cam shaft as in the machine of Patent No. 1,834,471, the construction for producing this adjustment comprising a vertical shaft 226, passing axially through the pattern cam shaft 224 and having a threaded engagement with a bearing for the lower end of the cam shaft. Rotation of the shaft 226 produces a vertical adjustment of the cam shaft and the shaft 226 is provided with an arm 228 by which the shaft may be turned manually to 25 adjust the cam shaft. To hold the cam levers away from the cams while the cam shaft is being adjusted, the shaft 230 upon which the cam levers are pivotally mounted, is provided with a number of shouldered collars 232, as in the machine of Patent No. 1,834,471 (see Fig. 2) which, when the shaft 230 is turned, engage the hubs of the levers and move the cam follower ends of the levers away from the cams. The present machine, however, is provided with a different means for turning the shaft 230, said means (see Fig. 11) comprising a longitudinally movable and rotatable shaft 231 provided with right and left-hand screw threaded portions, one of which portions screws into a sleeve pivotally mounted at the outer end of an arm 234 projecting from the shaft 230 and the other of which portions has a screw threaded engagement with a block 235 mounted to turn in a fixed bearing in the machine frame. One of the cam levers 238, not being mounted on the shaft 230, is moved away from the cam, as in the machine of Patent No. 1,834,471 by a slotted link connection 240 between an arm 241 operable with the lever and an arm 242 secured to the shaft 230. 30 35 40 45

The mechanism for automatically initiating the final stopping movements of the machine is actuated from the pattern cam shaft after it has made nearly a complete revolution. This mechanism acts to release the lock bolt 50 and permit it to move into engagement with the cam slot 48 of the main clutch member 38 and is substantially the same as the mechanism disclosed in Patents No. 1,791,176 and No. 1,834,471. This mechanism (see Figs. 6, 7, and 8) comprises the gear 212 at the upper end of the pattern cam shaft and a block 244 secured to the upper surface of the gear, which block, after the pattern cam shaft has made nearly a complete revolution, engages and swings backwardly a pawl lever 508, hereinafter described, and through the pawl 65 moves a lever 246 pivotally mounted at 248 on the machine frame. A sliding rod 250 is pivotally connected at its rear end to the lever 246 and at its forward end is arranged to engage the end of a dog 252 pivotally mounted at the left hand end 70 of a lever 254. The arrangement of these parts is such that as the pattern cam shaft nears the end of a revolution the lever 246 is rocked, the rod 250 is moved longitudinally towards the front of the machine and the lever 254 is swung for 75

wardly at its left hand end about its pivot 256. The right hand end of the lever 254 is connected by means of a slotted link 258 to the left hand end of another short centrally fulcrumed lever 260. The right hand end of the short lever is provided with a V-shaped recess in which the lower wedge shaped end of a vertical sliding control bar 262 rests (see Figs. 3 and 8). When the left hand end of lever 254 is moved forwardly, the right hand end containing the V-shaped recess of the short lever 260 is actuated to raise the vertically sliding control bar 262. As fully illustrated and described in Patent No. 1,791,176, connections to the control bar include a step by step timing device and a snap switch 264 having an actuating arm or lever 266 adapted to be actuated by an off-center spring 268 in one direction or the other according to the position of the clutch controlling mechanism. The switch is operated during the first movement of the control bar and electrical connections are made to the motor 14 to reduce its speed during the next three cycles of operation of the stitch-forming devices. The control bar is given a step by step upward movement in time with the rotation of the sewing cam shaft until the upper end of the bar strikes the latch 160, releasing the fingers 142 holding the lock bolt 50 out of engagement with the cam slot 48 on the main driven clutch member. At the same time, the latch 58 is allowed to rise by upward movement of the clamp block 158 on the link 148 connected with the retracting fingers 142. The entry of the lock bolt 50 within the cam slot 48 causes the driven clutch member to become disengaged from the main driver and wedged within the braking member 46 to arrest the movement of the main sewing cam shaft. The control bar 262 upon releasing the latch 160, is itself released from the step by step mechanism and returned to its lowest position in engagement with the V-shaped end of the short lever 260, which, during the final movements of the machine, has been restored to its neutral position. The control bar 262 may also be raised to stop the machine by a manually operable lever 270 (see Fig. 8) pivoted on the frame of the machine.

The jack and its supporting structure are substantially the same as in the machine of Patent No. 1,834,471, more fully described in U. S. patent to Laurence E. Topham and Alfred R. Morrill No. 1,616,714, dated February 8, 1927. The jack comprises a toe supporting arm 276 (see Fig. 1) rigid with the hollow spindle 278 and a heel supporting arm 280 pivoted at its lower end upon the upper end of the spindle. The jack support comprises a horizontal arm 282 (see Figures 2, 3, 4, 9 and 10) in the forward end of which the lower end of the jack spindle is rotatably mounted by means of a gimbal joint. The arm 282 is mounted by means of pivotal connections 286 to swing vertically upon a support 284, and the support 284 is pivotally mounted upon substantially vertical hollow bearing surfaces 288 and 290 carried by a frame 292 which is pivotally mounted on the main base 2 of the machine by horizontal bearings 294.

During the sewing operation, tipping and rotating movements are imparted to the shoe to maintain the shoe at all times in proper position, tipping movements being imparted by moving the lower end of the jack spindle forwardly and rearwardly of the machine, and laterally, and rotating movements being imparted by rotating the jack about the axis of the spindle. With the

exception of the arrangement of the cable through which the jack spindle is rotated, the mechanisms for producing these movements are substantially the same as in the machines of the patents above referred to. For moving the lower end of the jack forwardly and rearwardly, a cam lever 296 is provided, one arm of which is pivotally connected to the frame 292 by means of a link 298 and the other arm of which is arranged to engage one of the cams on the pattern cam shaft. The lateral movements of the lower end of the jack spindle are produced by oscillating the support 284 about its vertical bearings, the lower end of which support is provided with a forwardly projecting arm 300 which is connected by means of a link 302 to one arm of a lever 304, the other arm of which is engaged by a cam on the pattern cam shaft. To rotate the jack spindle, a helically grooved drum 306 is provided, having a downwardly extending pivot pin 308 journaled in the outer end of the horizontal arm 282 and the jack spindle is connected to the drum 306 through the gimbal joint above referred to. The drum is rotated by a cord or cable 310 wound substantially one and a half times around the drum and lying in the groove of the drum and secured against slippage by a clamp 312. From the drum one end of the cable passes over a pulley 314 on the base of the machine to a pulley 318 on a weight 316, and thence over a series of pulleys, as in the machine of Patent No. 1,834,471 to a control lever 374 hereinafter described. In the other direction, the cable passes rearwardly from the drum within enclosing flanges formed on the arm 282 and around a horizontally arranged sheave 320 on the arm, the inner circumferential portion of which sheave lies substantially tangent to the axis of the pivotal connections 286. The cable, after passing from the horizontal sheave is guided by an approximately vertically arranged sheave 322 rotatable on the support 284 and having a portion of its inner circumference tangential to the axis of the pivotal connections 286. The cable extending from the sheave 322 passes through the centers of bearings 288 and 290 and under a third sheave 324 mounted on bearings in the frame 292. The sheaves 322 and 324 are positioned so that the portion of the cable extending between them passes substantially through the axis of rotation of the vertical bearings. The cable passes from the sheave 324 and around a fourth sheave 326 also carried by the frame 292 and having a portion of its inner circumference approximately tangent to the axis of the horizontal bearings 294 fixed on the main frame of the machine. The cable, after passing from the sheave 326 is secured to a wheel 328 attached at the bottom end of a shaft 330 having its upper and lower ends mounted on bearings 332 and 334, respectively, upon the frame of the machine. The upper end of the shaft 330 is provided with a pinion which meshes with a segmental rack 338 on the outer end of a lever 340, the other end of which lever is engaged by a cam on the pattern cam shaft (see Fig. 4). By thus arranging the sheaves 320, 322, 324 and 326 so that portions of the spindle rotating cable 310 pass in substantial alignment or coincident with the respective axes of the pivot bearings of the members of the jack supporting structure relative movements of the different members in no way affect the length of cable between the grooved wheel and the actuated end of the cable. For this reason, other jack positioning movements do not interfere with the rotation of the jack. The use of the helically

grooved drum at the lower end of the jack rotating spindle also insures free and easy rotation of the jack about the axis of the spindle without irregular movements from interference between overlapping turns of cable.

Mechanism similar to that illustrated and described in Patents No. 1,616,714 and No. 1,834,471 is provided in the illustrated machine for adjusting the speed of the pattern cam shaft in accordance with the size of the shoe to be operated on. To this end the cam plate 220 (see Fig. 3) for controlling the movement of the pawl carriers 216 of the variable speed mechanism is pivotally mounted upon the frame of the machine and provided at its free end with a toothed segment portion meshing with a correspondingly toothed segment 344 (see Fig. 3) also pivotally mounted upon the frame of the machine. The segment 344 is actuated by an arm 346 movable with the segment and attached at its outer end to one end of a controller bar 348 acting when moved endwise in either direction to shift the cam plate 220. Movement is imparted to the controller bar by engagement of a pin 350 on a forward extension of a lever 352 with one of two inclined surfaces formed on the end of the bar 348 remote from the arm 346. The lever 352 is adjusted in accordance with the position given to the shoe in moving the jack into operating position with relation to the stitch-forming devices preliminary to starting the machine, as fully explained in the patents above referred to. In starting the machine, the controller bar 348 is moved bodily into engagement with the pin 350 through the action of a link 354 pivotally connected at one end to the controller bar and at the other to a lever 356 fulcrumed on the frame of the machine. As the lever 356 is rotated about its fulcrum point and the controller bar is moved into contact with the pin 350, the lever 356 is latched in position by engagement of a projection on the lever with a latch 358.

In the illustrated machine, the lever 356 for changing the speed adjustment of the pattern cam shaft is operated from connections to the power starting mechanism in starting the machine in operation. For this purpose, the slide 138 (see Figs. 7 and 8) connected with the crank shaft 68 on the power starting mechanism is formed at its lower end with rack teeth 360 engaging a pinion 362 rotating on a stud shaft fixed to the frame of the machine. The pinion 362 is attached to rotate with a gear 364 meshing with a second rack 366 on the end of a rod 368 slidably horizontally across the front of the machine base. The rod is normally tensed toward the left hand side of the machine by a spring 370 (see Fig. 3) fastened at one end to the rod and at the other to the frame. Adjacent an extension of lever 356 there is provided an upwardly extending pin 372 which engages the lever when the rod 368 is moved towards the right. Operation of the slide 138 from the power starting mechanism causes rotation of the gear 364 and movement of the rod 368 to the right, rocking the lever 356 to latched position and providing the proper adjustment for the speed of the pattern cam shaft in accordance with the size of a shoe.

In the present machine, the shoe is fed by the devices of the sewing mechanism acting directly on the shoe. In order to maintain the shoe in time with the position changing movements imparted to the shoe from a pattern cam shaft, an improved mechanism has been provided for co-ordinating the movements imparted to the jack by

the pattern cam shaft with the feeding movements imparted by the sewing mechanism. This improved mechanism comprises the control lever 374 mounted at 376 on the main base of the machine frame to swing in a horizontal plane and connected at its forward end through a lost motion device and a link 378 to the toe supporting arm of the jack. For moving the control lever 374, the central part is connected by means of links 380 and 382 to the end of the arm 241 which is operable with the cam lever 238 engaging a cam on the pattern cam shaft. The links 380 and 382 are pivotally connected together and to the free end of a swinging guiding link 386. The link 386 is fulcrumed upon a lever 388 which is held locked in position during the operation of a shoe. To adapt the machine for operation on shoes of different sizes, the lever 388 is pivotally mounted upon the machine base so that it can be adjusted to change the position of the fulcrum of the swinging guiding link 386. The fulcrum carrying lever 388 is held locked in adjusted position during the operation on the shoe by mechanism comprising a rod 390 pivotally connected to the rear end of the fulcrum carrying lever 388 and arranged to slide in a block pivotally mounted on the machine base. The rod 390 is engaged by the inner cam shaped ends of short levers 392 mounted in the block and the outer ends of these levers are connected by a pin and slot connection with a cross bar 394. This cross bar is pivotally mounted on the rear end of a rod 396, the forward end of which is pivotally connected to the central part of the controller bar 348. Rotation of the lever 356 during operation of the power starting mechanism in starting the machine moves the controller bar 348 and the rod 396 forwardly of the machine to lock the rod 390 in fixed position. The placing of a new shoe on the jack acts to release the lever 356, as explained in Patent No. 1,616,714, above referred to, so that the fulcrum carrying lever 388 is unlocked and adjustment of the mechanism for actuating the control lever can again be made by the movement of a newly jacked shoe to starting position in the machine.

The lost motion device between the control lever 374 and the link 378 comprises a small lever 398, the hub of which extends on either side of a lug 400 on the control lever through which lug a pivot pin 402 is fitted (see Figs. 13, 14 and 15). The lever 398 extends slightly to one side and forwardly from its pivot and is pivotally connected to the link 378 leading to the toe of the jack. On the opposite side of its pivot an extending arm of the lever 398 is arranged to oscillate between two adjustable set screws 404 and 406 threaded into lugs carried by the forward end of the control lever. An insulating member 408 is mounted on a horizontal pivot 410 in a recess formed in the lever 398, and carries an electric switch contact 412 for wiping two stationary contacts 414 and 416 mounted in insulating material at the end of the control lever 374. The contact 416 is made shorter than the contact 414 so that in one position with the lever 398 against the set screw 404 no conductive connection exists between the contacts but, when the lever 398 is thrust against the set screw 406, a circuit will be completed. Opening or closing of the circuit containing contacts 414 and 416 acts to vary the rotary speed of the pattern cam shaft through the gear train connecting it to the main driven clutch member, as will be described.

The train of gears, above described, for driving the pattern cam shaft from the main driven

clutch member is proportioned to cause the forward end of the lever 374 to move at a slightly slower rate than the toe portion of the jack as it is moved under the feeding action of the stitch-forming devices on the shoe. The difference in movement of these two parts reacts on the small lever 398, rotating it about its pivot pin to close an electric circuit connected between the contacts 414 and 416. This circuit, illustrated diagrammatically in Figure 13, comprises a flexible cable 418 carried by the control lever 374 and provided with wires connected to the contacts 414 and 416. Closing the circuit between contacts 414 and 416 energizes an electro-magnet 420, the armature of which acts to produce a change in the gearing through which the pattern cam shaft is driven. This gearing comprises a gear 422 loosely mounted to turn freely on a shaft 424 keyed to the sleeve 190 and on which shaft the low speed driving pinion 192 is fixed (see Fig. 12). Longitudinal displacement of gear 422 is prevented by set screws 426, threaded into the gear 422 and arranged with their inner ends extending into an annular groove 428 in the surface of the shaft 424. The gear 422 meshes with a gear 430 rotating with the sleeve 198 and the ratio of teeth between these gears is such that when the gear 430 is driven by the gear 422, a greater movement of sleeve 198 is produced than by a corresponding rotation of pinion 192 and the gear 194. The gear 430 is provided with a ring 432 having an inner conical frictional surface adapted to be engaged by the face of a correspondingly shaped member 434 keyed to the sleeve 198 and against which the ring is forced by a spring 460. The frictional engagement between the inner face of the ring 432 and the conical member 434 is normally sufficient to drive the sleeve but permits the gear 430 to rotate with relation to the sleeve 198 sufficiently to absorb the shock when the gear is put into operation. Movements produced by the pinion 192 and the gear 422 do not interfere on account of the overrunning action of the clutch 196 which permits the sleeve 198 to rotate faster when driven by the gear 430. The gear 422 is adapted to be rotated by a clutch member 436 sliding on the shaft 424 which is rotated from the short vertical shaft 188 driven from the main clutch. The member 436 is fixed to rotate with the shaft by a pin 438 extending diametrically through the member and through longitudinal slots in the shaft. The upper surface of the sliding member and the lower surface of the gear 422 are serrated with inter-engaging projections to establish a driving relation. The sliding clutch member 436 is moved into and out of engagement with the gear 422 by the movement of the armature of the magnet 420 through connections which comprise a split cylindrical block 440 fitting within a longitudinal hole in the shaft 424. The pin 438 passes through this block and thus connects the block with the clutch member. The magnet 420 is mounted directly below the shaft 424 on a bracket 441 and the armature of the magnet carries a short vertical rod 442 extending upwardly from the armature core of the magnet. The block 440 is provided with a recess surrounding the head of a pin 444 threaded at its lower end in a block 446 clamped on the upper end of the vertical rod 442. A spring 448 surrounds the pin 444 and is interposed between the block 446 and the lower end of the cylindrical block 440. The construction and arrangement of these parts are such that a movement of the armature of the magnet 420 when the magnet is energized forces the clutch member

436 yielding into engagement with the gear 422, and a movement of the armature in the opposite direction when the magnet is de-energized, moves the clutch member out of engagement with the gear. 5

The circuit of the magnet 420 is energized to increase the speed of rotation of the pattern cam shaft from a source of power 450 (see Fig. 13) through relay contacts 452 and through connections to the coils surrounding the armature of the magnet. Contacts 452 are connected to energize the magnet 420 by a relay coil connected to one terminal of a low voltage transformer 456 and to the contact 414 mounted on the control lever 374. The contact 416 is connected to the other terminal of the transformer. High voltage connections between the transformer and the source of power 450 serve to furnish current to actuate the relay. The transformer 456 and the relay 454 are mounted in a box 458 attached to the side of the machine base, connecting wires being carried in flexible metal conduits. Connection between the contacts 414 and 416 is interrupted as soon as the control lever 374 has caught up with the feeding movements of the stitch forming devices and the change speed gear is shifted back again to low speed by de-energizing the magnet 420. This shifting continues throughout the stitching operation in accordance with the variations in movement between the shoe supporting jack and the control lever, the relative periods of low and high speeds providing sufficient range of speed variation. 25

When the sewing mechanism is brought to rest by disconnecting the main driven clutch member 38 from the main driver, an auxiliary mechanism similar to that of the machines of Patents No. 1,616,714 and No. 1,834,471 is automatically connected to the main driver 18 in substantially the manner disclosed in said patents. 35 This mechanism comprises an eccentric 466 (see Figs. 3, 7 and 8) mounted to turn loosely upon a hollow stud formed on the machine frame below and in axial alignment with the shaft 30 to which the power driver 18 is pinned. Vertically below the eccentric 466 is a clutch block 468 mounted to slide longitudinally on and rotate with a continuously rotating shaft operated through a reduction gear from the lower end of the shaft 30. The opposed faces of the clutch block 468 and the eccentric 466 are provided with teeth through which the eccentric can be driven from the clutch block whenever the block is raised into engagement with the eccentric. The block 468 is engaged by the forked arm of a lever 470 provided with a projection arranged to be engaged by a shoulder on the lower end of a vertical rod 472. The upper end of this rod is connected to an arm 474 on one end of the shaft 54 upon which the bolt carrier 52 is fixed. The lower end of the rod 472 is arranged to move vertically between two pins 476 projecting upwardly from a short lever 478 pivoted concentrically with the lever 254 which is operated by the pattern cam shaft during the last part of its revolution. The lever 478 is acted upon by two spring pressed plungers 480 mounted in the lever 254 to maintain the lever 478 yielding in alignment with the lever 254. With this construction, when the lever 254 is swung forwardly to actuate the vertical sliding control bar 262, the lever 478 will be retained in its original position by reason of the engagement of the side of the shoulder on the rod 472 with the projection on the lever 470. As the lock bolt carrier 52 operates first in a clockwise 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

direction as viewed in Fig. 8 and then in a counter-clockwise direction, it will raise and lower the rod 472, the rod being moved forwardly by the lever 478 as the shoulder on the rod passes above the projection on the lever 470 during the upward movement of the rod and actuating lever 470 during the downward movement to move the clutch block 468 into engagement with the eccentric 466. To permit the clutch block to move away from the eccentric and thus throw the eccentric out of operation, the rod 472 is moved rearwardly to release the lever 470. This takes place after the eccentric has made a complete revolution. To thus move the lever 478 rearwardly, the lever (see Fig. 3) is provided with gear teeth engaged by teeth on one arm of a lever 482. At its other end, the lever 482 is provided with a member 484 adapted to be engaged by an arm 486 projecting from a rock shaft 488 which is moved forwardly and backwardly during the rotation of the eccentric, the construction being such that during the forward movement of the arm the lever 482 is not moved but, during the return movement of the arm, the member 484 is actuated by the arm 486 to return the lever 482 to its original position and thus move the rod 472 out of engagement with the lever 470. By this mechanism, movement of the lever 254, as the pattern cam shaft approaches its stopping position, causes the rotating clutch block 468 to be moved into operative relation with the eccentric 466 to drive the eccentric through one complete revolution at the end of which the clutch block is moved away.

35 The mechanism actuated by the eccentric 466 includes the eccentric strap 490 (see Fig. 7) and the rock shaft 488 above referred to, which is oscillated by an arm 491 pivotally connected to the eccentric strap. From the shaft 488 the mechanism is actuated through which the jack is moved outwardly away from the sewing devices, and also the mechanism through which a movement is imparted to the pattern cam shaft to complete its rotation so as to cause the jack to be reversely rotated to its initial position. These mechanisms are substantially the same as the corresponding mechanisms of the machines disclosed in Patents No. 1,616,714 and No. 1,834,471, above referred to, except that in the present machine, no provision is made for depressing the jack before moving it outwardly.

For moving the jack outwardly, the rock shaft 488 is provided at its lower end with an arm 492 carrying bevel gear teeth which mesh with corresponding teeth formed on a segment secured to a horizontal shaft mounted in the front part of the machine. Upon this horizontal shaft an arm or lever is mounted to engage the upper surface of a bar 494 (see Fig. 2). The bar is moved longitudinally toward the front of the machine by its contact with this mechanism, against the action of a spring 496 stretched between the inner end of the bar 494 and the frame of the machine. The bar at its forward end is connected by a ball and socket joint to the central part of the jack spindle and is pivotally connected at its rear end to the lower end of an arm 498 pivotally mounted in a bracket depending from the top plate of the machine base. The spring 496 acts during the normal operation of the machine to retain the lateral margin of the outsole in engagement with the stitch-forming devices. Mechanism including a cable 500 (see Figs. 1 and 3) passing over pulleys and having its ends secured to the arm 282 and acted upon intermediate

its ends by a spring 501 yieldingly supports the jack vertically.

The final movement of the pattern cam shaft is produced through connections between the pattern cam shaft and the arm 492 at the lower end of the rock shaft 488. These connections are similar to those disclosed in Patents No. 1,616,714 and 1,834,471 and consist of a rod 502 (see Fig. 3), the forward end of which is pivotally connected to the arm 492 and the rear end of which is connected to one arm of a bell crank 504, pivotally mounted on the frame of the machine. The other arm of the bell crank carries the pivot 506 for the pawl lever 508 hereinbefore referred to. The pawl lever 508 is provided at its outer end with a roll 507 which bears against a track at the outer end of the stationary arm 509 secured to the top of the base 2 of the machine, extending above the gear 212 on the pattern cam shaft. The pawl lever is acted upon by a spring 511 which holds the roll 507 in contact with the track at the outer end of the arm 509 with the pawl lever in position to be engaged by the block 244 on the gear 212. As the pattern cam shaft nears the end of its rotation, the pawl lever 508 is raised and thereby actuates the lever 246 to throw the stop mechanism into operation, as hereinbefore described. As the rotation of the pattern cam shaft ceases, the pawl lever 508 rests upon the block 244 and remains in this position until the eccentric 466 is thrown into operation. During the forward swinging movement of the arm 492, the bell crank 504 is rocked in a direction to move the pawl lever 508 longitudinally so that it drops behind the block 244. As the arm 492 swings back to its original position during the latter part of the rotation of the eccentric, the end of the lever 508 strikes the end of the block 244 and turns the cam shaft a sufficient distance to complete its revolution. As the cam shaft completes its revolution, the cam levers which engage the cams are permitted to move toward the center of the shaft and thus the jack is reversely rotated and the other parts of the machine connected to the cam levers are returned to their starting position.

The illustrated machine is also provided with mechanism which may be thrown into operation by the operator after the sewing mechanism and pattern cam mechanism are stopped to turn the pattern cam shaft backwardly. This mechanism is the same as that disclosed in Patent No. 1,616,714, and is thrown into operation by rocking the lever 470 in a direction to depress the clutch block 468 instead of raising it. In the present machine, however, manual instead of automatic means are provided for thus rocking the lever 470, this means consisting of a manually operable bell crank lever 520 (see Fig. 8) pivoted at 522 on the machine frame and having one arm formed as a handle and the other arm forked to engage the outer end of the lever 470.

The stitch-forming devices (see Figs. 16, 17 and 18) including the needle, indicated at 540, the awl at 542, the work support at 544, the presser-foot at 546, the shuttle at 548, the looper at 550 and other mechanisms to be referred to hereinafter are timed to pass a needle loop over the locking thread while the awl is penetrating the work for a new stitch. In order to facilitate the use of this timing arrangement in an automatic shoe machine where a backward rotation cannot be conveniently imparted to the sewing cam shaft at the conclusion of the sewing operation, the needle is mislooped during the last operation, and no loop of needle thread is carried

through the work during the withdrawal of the needle. In the machine illustrated, this result is secured by a change in the path of the looper during the last cycle of the stitch-forming devices. The looper 550 is fixed to the forward end of a horizontally arranged looper carrier 552 which is pivoted at its rearward end to the horizontal arm of a lever 556. This lever is provided with an elongated hub which is pivotally mounted at its upper end on a bracket 562 fixed to the frame of the machine and at its lower end is pivotally supported on a boss 564 in the main frame by a stub shaft. The looper carrier 552 slides through a block 566 having horizontal upper and lower surfaces engaging parallel guiding surfaces 568 and 570 on the main frame (see Figs. 16 and 35). Sliding movements of the looper carrier 552 through the block 566 to produce forward and rearward movements of the looper are imparted by the lever 556 which is provided with a forwardly extending arm engaging a cam on the sewing cam shaft. Movement of the looper carrier 552 about its pivotal connection with the lever 556 produces lateral movement of the looper and this movement is imparted to the looper carrier by a cam actuated lever 572, the forward end of which is pivotally connected to the block 566. The lever 572 instead of being actuated directly from a cam on the sewing cam shaft is mounted upon a yoke-shaped member 576, the elongated hub of which is pivotally mounted at its upper and lower ends in bosses 580 and 582 formed in the bracket 562 and the frame of the machine respectively and which is provided with an arm engaging a cam on the sewing cam shaft. During the sewing operation, the lever 572 is rigid with the yoke-shaped member 576 so that the lever and yoke-shaped member act as a single cam actuated lever to impart the required lateral movements to the looper carrier to cause the looper to lay the thread in the hook of the needle. To enable the path of the looper to be changed so that the needle may not be looped during the last cycle of the stitch-forming devices, the lever 572 is pivotally mounted intermediate its ends upon the yoke-shaped member 576 and is engaged at its rear end by a link 592 of a toggle, the other link of which consists of a segment 590 loosely mounted on the stub shaft at the lower end of the hub of the lever 556. The arrangement of this toggle is such that when the toggle is in straightened or set position the pivotal connection between the toggle link 592 and the rear end of the lever 572 is concentric with the pivot of the yoke-shaped member 576. This is the position of the parts when the looper is performing its normal looping operation.

During the last stitch-forming movements of the sewing mechanism, the segment 590 is rocked to the position shown in Figure 21, causing a lateral movement of the looper relative to its normal position so as to misloop the needle. For causing this movement, the segment 590 meshes with a corresponding toothed segment 594 loosely mounted upon a shaft 596 horizontally disposed in the frame of the machine. The segment 594 is operated by an integral arm 598 having a pivotal connection to a link 600. The outer edge of the arm 598 is provided with indentations to cooperate with a spring pressed plunger 602 slidable radially of the shaft 596 in the sewing frame (see Fig. 20). The upper end of the link 600 is provided with an enlarged extension in the form of a sleeve 606 screw threaded upon the link and

adjustably secured by means of a locking nut 604. The sleeve 606 slides freely through a block 607 (see Fig. 30) pivotally mounted by means of a laterally extending stud 608 in the outer end of a lever 610 rotatably mounted on a shaft 612 journalled in the frame of the sewing mechanism. Projecting from the upper end of the sleeve 606 is an adjustable screw 609 provided with a head somewhat larger than the sleeve so that during the upward movement of the lever 610, the head of the screw may be engaged by the block 607 and an upward movement imparted to the link 600 to move the arm 598 upwardly into the position indicated in Figure 20. The lever 610 is operated by a gear segment 614 extending from the opposite sides of its bearing hub on shaft 612 and meshing with a corresponding segment 616 attached to the end of a short stub shaft 618, fulcrumed in the frame of the machine. The stub shaft 618 is provided at its right outer end with an enlargement 620 having a slot cooperating with a tongue (see Figs. 7 and 20) formed on an enlargement 622 at the end of a short shaft fulcrumed on the frame of the power drive in alignment with and rotated by the shaft 54 (see Fig. 8) on which is fixed the bolt carrier 52 for the stop motion. Rotation of the lock bolt carrier 52 during the final movements of the machine operates through the mechanism just described to misloop the needle and prevent the formation of an uncompleted stitch at the end of the seam. The lock bolt 50 slidable in the carrier engages the cam slot 48 in the main driven clutch member at the highest position of the slot and as the bolt is moved downwardly with the carrier, the shaft 54 is rocked in a clockwise direction, as viewed in Figure 8. This movement produces a corresponding rotation of shaft 618 and segment 616. The segment 614 meshing with segment 616 is rocked in a reverse direction to raise the outer end of the lever 610 to cause an upward movement of link 600. The arm 598 is shifted upwardly to the position shown in Figure 20, acting on the toggle link 592 through segments 590 and 594 to displace the rearward end of the looper operating lever 572, moving the looper to one side of its normal operating position.

The looper is returned to its normal operating position when the machine is restarted by a connection to the power starting mechanism. Above the upper end of the link 600 a finger 626 extends from the shaft 612. Keyed to the shaft is a hub 628 (see Figs. 5, 30 and 34) provided with a segmental extension 630. A short bolt 632 extends through an arcuate slot in the extension 630 and into threaded engagement with the finger 626 adjacent the shaft 612. The hub 628 and the hub portion of the finger 626 surrounding the shaft 612 are provided with inter-engaging serrations and the bolt 632 holds these parts in fixed angular relation so that rotation of the shaft 612 produces a corresponding movement of the finger 626. The shaft 612 is provided at its outer end with an arm 634 (see Fig. 20) pinned to the shaft and formed at its outer end with a clevis 636. The crank shaft 68 of the power starting mechanism operates the arm 634 through an eccentric 638 (see Fig. 5) rotating with the shaft and connected with the clevis 636 by means of a pitman 640. Rotation of the crank shaft 68 of the power starting mechanism through one revolution rocks the shaft 612 first in a clockwise direction to thrust the finger 626 downwardly against the link 600 and then in a reverse direction to its original position. Movement of the

link 600 downwardly restores the rearward end 588 of the lever 572 in alignment with the bearing of the hub 578 and returns the looper to normal operating position by sliding the sleeve 606 through the block 607. The plunger 602 acting against the outer surface of the arm 598 prevents displacement of the arm except when positively operated.

The operations next performed after the needle 10 is mislooped during the final stopping movements of the machine include cutting the threads of the last completed lockstitch and releasing the grip on the projecting edge of the shoe sole of the work support and the presser-foot. The thread cutter for severing the threads is operated from a continuously driven mechanism and includes a momentarily actuated one-revolution clutch. The same clutch also operates mechanism for releasing the presser-foot from engagement with 20 the shoe sole.

The thread cutter mechanism comprises a knife edged member 660 (see Fig. 18) carried upon a forwardly and laterally bent arm 662 pivotally mounted upon a horizontal stud screw 664 having its end threaded into the forward end of the presser-foot 546. The presser-foot 546 is pivotally mounted upon a screw 666 carried by the frame of a feed slide or carriage 668. An operating connection is made to the arm 662 through a link 672 pivotally attached at its ends to the arm 662 and to an arm 674 fulcrumed on a stud 676 carried by the feed slide 668. The rearward end of the link 672 is movable by the arm 674 to and from the center of screw 666 upon which the presser-foot is mounted and, when it is aligned with the axis of the screw, movement of the presser-foot about the screw produces no relative movement of the thread cutter. The arm 674 may be oscillated about the stud 676 through the action of a series of gear teeth 678 formed on the arm 674 adjacent the end surrounding the stud 676. The teeth 678 engage a gear segment 680 fulcrumed upon a screw 684 mounted in a bracket 682 extending from a fixed part of 45 the frame of the machine. Oscillation of the gear segment 680 imparts movement to the arm 674, and through the link 672 to the arm 662, moving the cutting knife 660 downwardly in a circular path about the stud screw 664 and into contact with the upper tread surface of the sole of a shoe indicated at 686 as supported between the presser-foot and the work table (see Fig. 17). The knife edged member is arranged to pass obliquely beneath the lower work engaging face 50 of the presser-foot and enter the substance of the shoe sole to sever the threads. Reverse movement of the gear segment 680 withdraws the thread cutting knife 660 from engagement with the shoe sole and returns it to normal inoperative position.

The gear segment 680 is formed with an arm 688 which is pivotally connected at 690 to the lower end of a vertical link 692. The upper end of link 692 (see Fig. 17) is pivoted at 694 to an eccentric strap member 696 having its rearward end fulcrumed on a screw 698 threaded into the lower end of a link 700 pivoted at 702 on the frame of the machine. The eccentric strap member 696 is arranged in a substantially horizontal position with the link 700 positioned at right angles to it so that the upper end of the vertical link 692 will be reciprocated up and down and will move forwardly and rearwardly to follow the movements of an eccentric 704 surrounded by the eccentric strap 696. Rotation of the eccentric

704 causes the gear segment 680 to be oscillated and the thread cutter 660 to be actuated.

The eccentric 704 for operating the thread cutter is driven from the main power driver 18 through a train of gears including the helical gear teeth 62 (see Figs. 5 and 6) formed on the power driver, gear 64 meshing therewith, spur gear 10 rotating with gear 64 and meshing with gear 72 on the countershaft 74 and a gear 708 meshing with the gear 72 and fixed upon a short 10 rotating shaft 710 journaled in the frame. The shaft 710 also carries a gear 712 fixed to the shaft and meshing with a gear 714 fixed to a shaft 716 passing through the eccentric 704 and rotating continuously so long as the main driver 15 of the machine is in operation. Connection between the shaft 716 and the eccentric is made during one revolution through the action of a Horton clutch of usual construction having a control member 718 held against rotation by contact 20 with an abutment 720 slidably mounted upon a vertical rod 722. The rod 722 is fixed to one end of an arm 723 pivoted at its upper end at 730 on the sewing frame. The abutment 720 normally engages a projection 724 from the control member 718, and is yieldingly maintained in position on the rod 722 by a spring 726 secured in place by a collar 728 pinned to the lower end of the rod. Movement of the abutment out of engagement with the projection on the member 718 causes 30 the eccentric 704 to rotate through one revolution, at the end of which, the projection again strikes the abutment and the rotation of the eccentric is arrested. Movements of the abutment into and out of engagement with the projection on the 35 member 718 are produced by oscillating the arm 723 about the pivot 730. The abutment is normally held against the one-revolution clutch by a compression spring 732 acting between the machine frame and a projection from the arm 723 40 above the pivot 730. The clutch is effectively retained in uncoupled condition by a pawl 734 pivoted at 736 to the arm 723. The pawl has a right angle arm 738 extending beneath a spring pressed plunger 740, and cooperates in a well 45 known manner with ratchet teeth 742 formed on a driven part of the one-revolution clutch, to prevent dragging of the clutch after being released or opened by the engagement of abutment 720 with projection 724. When the abutment 720 is 50 withdrawn from the projection 724, the pawl 734 is held out of engagement with the clutch by a set screw 744 arranged to contact with the horizontal arm 738 of the pawl.

The clutch for coupling the eccentric 704 to 55 the shaft 716 to actuate the thread cutter is thrown into operation through connections actuated from the sewing cam shaft of the machine so that the thread cutter is actuated in timed relation to the movements of the sewing devices. 60 The abutment 720 is withdrawn from the projection 724 on the controlling member of the clutch by means of a pawl 746 acting on a shoulder 748 formed on the collar 728 (Figs. 17 and 23). The pawl 746 is pivotally mounted at 750 on a bell 65 crank arm 752 rotating on a sleeve 754 supported on a horizontal shaft 756 extending across the front of the sewing machine (see Fig. 16). The forward end of the pawl is maintained in a lowered position to engage the shoulder 748 by a 70 spring pressed plunger 760 bearing against the pawl and being slidably mounted in the arm 752. The other arm 762 of the bell crank is pivotally connected at its end to a link 764 extending downwardly and provided at its lower end with a 75

- pointed projection 776 arranged when the thread cutter is to be thrown into operation to be moved into the path of a constantly vibrating lever actuated from the sewing cam shaft. Downward movement of the link 764 acts to rock the bell crank arm 752 and, through the pawl 746, swing the arm 723 to move the abutment 720 out of engagement with the projection 724 on the control member of the one-revolution clutch.
- 10 The link 764 is moved downwardly by the action of an arm 788 extending from a lever 790 (Figs. 17 and 20) loosely mounted on the shaft 772, the arm striking the projection 776 on the link. The inner end of the lever 790 extends into the path 15 of an enlargement 792 on a cam 794 rotating with the main sewing cam shaft 166 of the machine. The angular position of the enlargement 792 is so related to the needle and awl actuating cams that both the needle and awl 20 will be out of engagement with the work when the enlargement 792 operates the lever 790 to throw into operation the one-revolution clutch for cutting the thread. This arrangement guards against interference by the thread cutter 25 with the awl or the needle, and prevents operation of the thread cutter until the needle has come to rest.
- The mechanism for actuating the thread cutter is thrown into operation by a connection 30 from the stop mechanism which throws out the main driving clutch. As has been stated, the mechanism for actuating the thread cutter is thrown into operation by moving the pointed projection 776 on the lower end of the link 764 35 into the path of the arm 788 on the cam actuated lever 790. For so moving the projection 776, the lower end of the link 764 is connected at 766 to the outer end of a link 768, the inner end of which is pivotally mounted on one arm of a bell crank 770 pivotally mounted on the short fixed shaft 772, the arrangement being such that the link 768 and the arm of the bell crank 770 form a toggle joint between the lower end of the link 764 and the pivot shaft 772. During the normal 40 operation of the machine in sewing a seam, the toggle joint is in its broken position, as illustrated in Figure 20 in which position the projection 776 is out of the path of the arm 788 on the lever 790. The projection 776 is moved into 45 the path of the arm 788 by oscillating the bell crank 770 so as to straighten the toggle. For so oscillating the bell crank, a link 771 is pivotally connected at its forward end to a downwardly extending arm of the bell crank, and at 50 its rear end is provided with a pin 778 having a sliding engagement with a horizontal slot formed in a block 780, which block is adjustably secured by a bolt 800 to the slotted forward end of a link 802. At its rear end, the link 802 is pivotally 55 connected at 804 to the upper end of an arm 806 extending from the enlargement 620 on the shaft 618 which is operated by the bolt carrier 52 of the mechanism for throwing out the main clutch, as hereinbefore described. In throwing 60 out the main clutch, the shaft 618 is first rocked in a clockwise direction, and during this movement, the link 802 is moved rearwardly until the end of the slot in the block 780 strikes the pin 778. Continued movement of the link 802 and 65 block 780 acts through the link 771 to swing the bell crank 770 into a position in which the toggle formed by the bell crank and the link 768 is straight, thereby moving the point of projection 776 into the path of the arm 788 on the cam actuated lever 790. This straightening move-

ment of the toggle occurs just before the sewing cam shaft stops and in the stopped position of the cam shaft the enlargement 792 on the cam 794 is either in engagement with the lever 790 or has been moved to a position slightly beyond the 10 lever. When the toggle formed by the link 768 and bell crank 770 is in its straightened position, the projecting center pivot pin 782 of the toggle extends just above a stationary bracket 784 adjustably secured to the frame of the machine by 15 bolts 786. As the link 764 is moved downwardly by the engagement of the arm 788 on the cam actuated lever 790 with the pointed projection 776, the link 768 is swung downwardly about the pivot pin 782, downward movement of which is 20 prevented by the bracket 784. During this downward movement of the link 768, the outer end of the link moves to a position in which the central pin 782 of the toggle is above the line connecting the pivotal points 766 and 772 at the outer ends 25 of the toggle. As the parts of the toggle assume this position, a spring 807 (see Fig. 20) connected between the frame of the machine and the outer end of the link 768 continues the 30 braking movement of the toggle sufficiently to move the projection 776 out of the path of the arm 788 on the lever 790. As soon as the projection 776 is freed from the arm 788 on the lever 790, the bell crank 752 carrying the pawl 746 is restored to its original position by means 35 of a spring 796 stretched between the outwardly extending arm 762 of the bell crank and the frame of the machine.

More than one revolution of the one-revolution clutch for operating the thread cutter is prevented by a lever 808 fulcrumed loosely on the screw 698 and provided with a short arm to which one end of a tension spring 810 is attached, the other end being secured to the frame of the machine. The lower end of the lever 808 bears upon 40 a cam surface 812 on a driven part of the one-revolution clutch. The part of greatest radius of the cam surface 812 acts against the lower end of the lever 808 to thrust it against the inner end of the pawl 746. The pawl 746 is rocked 45 about its pivot 750 by the lever 808 so that its outer end is raised from the shoulder 748 to break the connection between the bell crank arm 752 and the clutch releasing abutment 720. The cam 812 is arranged to act just before the projection 724 strikes the abutment 720 so that a single revolution only of the clutch will take 50 place.

The thread cutting knife 660 in the case of the present machine is constructed with flange 55 portions extending at right angles to each other, sharpened at their ends, and bent longitudinally into an arc shape. The knife is removably fixed to the arm 662 by a screw 813 so that its center of curvature will coincide with the center of the 60 stud screw 664 about which it oscillates. The action of the knife 660 is more clearly shown in Fig. 19 which indicates the thread cutting position of the knife at the extreme end of its stroke. The edge of the shoe 686, indicated at 814, is held 65 between the upper surface of the work support 544 and the presser-foot 546. The end of the seam comprising a series of stitches 816 terminates in projecting ends of the needle thread 818 and the locking thread 820 extending toward 70 their respective sources of supply. The stitches 816 are formed by concatenating the two threads with a shallow lock adjacent the upper tread surface of the shoe. The thread cutting knife 660 acting against the surface, enters the substance 75

of the shoe sole to sever the locking thread at 822 adjacent the surface and the needle thread at 824 as near as possible to the surface so that a minimum amount of thread will be wasted and the projecting ends 818 and 820 of the needle and locking thread, respectively, may be withdrawn from the work without resistance. The small incision made by the knife may be pressed back to form a smooth surface and, since the thread cutter operates only upon the completion of an outseam which normally is terminated within the breast line of the heel seat area, the incision will be concealed from view by the attachment of the heel.

Subsequent to the operation of the thread cutter the projecting edge of the outsole is released from the machine by raising the presser-foot. The presser-foot of the machine is thrust into gripping engagement with the tread surface of a shoe sole by yielding means acting through a locking wedge block system similar to that described in the U. S. patent to Ashworth No. 1,756,502, granted April 29, 1930. The presser-foot acting about the pivot screw 666 as a center is clamped downwardly against and is released from the work through connections to an arm 826, extending rearwardly from the portion of the presser-foot adjacent the pivot. The arm is operated by a wedge block 828 connected to the arm 826 by a link 830 having a ball and socket attachment to both the arm and wedge block, in order to permit the presser-foot to move back and forth in the line of feed with the feed carriage. The wedge block 828 slides within a guide block 832 screwed to the sewing frame and is forced upwardly by a locking wedge block 834 also sliding within the guide block. The wedge block 834 is yieldingly pressed toward a raised position by a rod 836 sliding at its lower end in a bracket 838 fixed to the main base of the machine (see Fig. 6). The rod 836 carries a spring 840 compressed between the bracket 838 and a collar 842 held in place on the rod 836. The upper end of the rod is connected with the locking wedge block by a universal joint. The wedge block 834 is constructed with a groove 844 cooperating with a guiding rib extending from the guide block 832. During the sewing operation of the machine the wedge block 834 is moved downwardly intermittently in time with the feeding movements by the action of an oscillating arm 848 carrying a spring pressed serrated member 849 at its end, adapted to engage corresponding serrations in the side of the wedge block. The serrated member is pressed away from engagement with the wedge block by a finger 850 fixed in the sewing frame and positioned to strike the member at the upper end of its stroke. At the time the serrated member 849 is moved away from the wedge block 834, the presser-foot is locked in engagement with the work by the spring 840 acting freely upwardly against the wedge block. Downward movement of the serrated member 849 produces a uniform releasing action of the presser-foot regardless of the thickness of the work. The arm 848 which carries the serrated member 849 is actuated by an upwardly extending arm 853 (see Figs. 6 and 17) having a cam follower engaging a cam on the sewing cam shaft. During the final movements of the machine the wedge block 834 is forced downwardly to release the presser-foot by the engagement with a lug 846 on the wedge block of a pawl 852 pivotally mounted at 854 on the end of an arm 856 (see Fig. 20) loosely fulcrumed on the horizontal shaft

596 which carries the segment for moving the looper to mislooping position. During the normal operation of the machine, the pawl 852 assumes a position at the rear of the lug 846 with its forward edge riding on the rear surface of the lug (see Fig. 17), and is yieldingly maintained in this position by a spring 858 having one end secured to the arm 856 and the other end to a bell crank member 860. The bell crank is also pivoted to the arm 856 at 862 and is connected to the pawl 10 852 by a link 864, the bell crank member 860 and the link 864 acting as a toggle. The link 864 is provided with an extending finger 865 to operate with a lug 867 on the bell crank for maintaining the toggle in straightened or set position 15 under the influence of the spring 858. The S-shaped arm is connected at its forward end to one end of a short link 868, the other end of which link is connected to an extension 866 of the arm 688 forming a part of the thread cutter actuating 20 mechanism, as previously described. The first movement of the arm 688 is in a downward direction for the purpose of operating the thread cutter. This movement rocks the extension 866 upwardly about the horizontally arranged pivot 25 screw 684 on which the lever arm is fulcrumed. During this movement, the pawl 852, under the action of the spring 858 snaps into vertical alignment with the lug 846 on the locking wedge block, as shown in Fig. 18. The upward movement 30 of the arm 688 withdraws the thread cutting knife 660 from the work and moves the pawl 852 downwardly against the lug 846 to release the presser-foot from gripping engagement with the work, as in Fig. 20. The presser-foot is raised 35 from the work by a light leaf spring 869 screwed to a fixed part of the machine and bearing at its free end against the under side of a pin extending laterally from the presser-foot 546.

The operation of the auxiliary one-revolution 40 clutch for driving the thread cutter and releasing the presser-foot must take place before the jack is given its final movements with relation to the stitch forming devices. In order to insure that these operations will not interfere with each 45 other, the driving shaft 716 for operating the thread cutter clutch is geared to rotate at a high speed, relatively to the speed of the shaft which carries the clutch block 468 for driving the jack actuating mechanism. 50

Before starting the machine into operation on a new shoe, the jack is moved manually into position with the projecting edge of the outsole between the work support and presser-foot. The handle 110 is then actuated to throw the power 55 starting mechanism into operation which immediately acts through suitable connections to move the pawl 852 out of engagement with the lug 846 on the locking wedge block 834 so as to permit the presser-foot to move into clamping 60 engagement with the shoe sole. These connections comprise the bell crank member 860 (see Figs. 6 and 20) and a lever arm 870 which is loosely fulcrumed on the rock shaft 612 and is provided at its lower end with a segmental surface 65 engaging the downwardly extending arm of the bell crank member 860. The arrangement is such that a movement of the lower end of the lever arm 870 to the left, as viewed in Figure 20, swings the bell crank lever 860 about its pivot 862 and, 70 through the link 864, withdraws the pawl 852 from engagement with the lug 846. The rock shaft 612 is operated from the power starting crank shaft 68 through the pitman 640 as hereinbefore described, and movement is imparted to 75

the lever arm 870 from the rock shaft through the hub 628 (see Figs. 5, 20 and 30) which is pinned to the shaft 612 and provided with a segmental extension 630 projecting between lugs

- 5 872—874 on the hub of the lever arm arranged to contact with set screws in the lugs as the shaft 612 is rocked. During the first movement of the shaft 612, the extension 630 strikes the set screw in the lug 874 and moves the lever against the 10 lower arm of the bell crank member 860, breaking the alignment of the toggle between the S-shaped arm 856 and the pawl 852 and moving the pawl out of alignment with the lug on the locking wedge block 834. This permits the locking wedge 15 block to move the presser-foot into engagement with the work under the influence of the spring 840, as shown in Fig. 17. The return movement of the rock shaft 612 causes the extension 630 to strike the set screw in the lug 872 and retract 20 the lever arm 870 so that the toggle connection between the S-shaped arm and the pawl 852 may again be aligned at the end of the operation on a new shoe.

While a completed shoe is being removed from 25 operative relation with the stitch-forming devices, the end of the needle thread is pulled from engagement with the shoe sole and hangs loosely over the forward edge of the work table in the position shown in Fig. 23. The thread is cut off 30 close to the work while the shoe is retained on the work support and the short length of thread left extending from the work table is not so great as to be objectionable when drawn up into the sole in forming a seam on a new shoe.

- 35 In order to insure that the needle thread will not be pulled from contact with a new shoe as the first stitch is being formed, means is provided for withdrawing a length of thread from the supply prior to the formation of the initial stitch. The 40 needle thread 818 ordinarily extends from between the work and the work table 544, downwardly about the end of the main take-up member 876 (see Fig. 18) fixed to a shaft 878 journaled in the frame of the machine, over a pulley 880 mounted 45 on a stationary bearing pin on the frame of the machine, and over a rotatable roll 882 at the end of an auxiliary take-up member 884, oscillating concentrically with the main take-up member on the shaft 878. From the auxiliary take-up 50 55 the thread extends around a pulley 886 rotating on the shaft 878, concentric with the axis of rotation of both the main and auxiliary take-ups, thence rearwardly through an aperture in the sewing frame (see Fig. 23) to a one-way gripper 888, around a tension wheel 890 of the usual construction, rotating with a shaft 892 journaled in a rearwardly extending bracket 893 on the sewing frame of the machine, to a wax pot or other source of supply of waxed thread. The main 60 take-up member 876 is shielded by an arcuate guard 894 fixed to the sewing frame. At the right end of the tension wheel shaft 892, as shown in Figs. 5, 20, 31, 32 and 33, a ratchet wheel 895 is pinned. To rotate the ratchet, a spring pressed 65 pawl 896 is pivoted at 898 to a yoke 900, surrounding the ratchet and rotating loosely at the end of the shaft 892. The pawl 896 is operated by a link 902 extending from the pivot 898 in a vertical direction and the link is actuated by the end 70 of an arm 904 clamped rigidly to the shaft 612. The movement imparted to the ratchet wheel 895 by the pawl 896 is adjustable by means of a movable shield plate 906 fixed to the bracket 893 and provided with an enlargement over which the 75 pawl 896 rides, for withdrawing it from engage-

ment with the ratchet wheel. The shield plate may be adjusted in any desired angular position by loosening a screw 908 entered in a slot 910 formed in an enlargement on the shield plate. As the power starting crank shaft 68 is rotated, the 5 shaft 612 is rocked, causing the pawl 896 to rotate the ratchet wheel 895 in a direction to withdraw a supply of thread dependent upon the adjustment of the shield plate 906. This adjustment may be set to provide sufficient thread to 10 relieve tension by the auxiliary take-up during the initial stitch on a new shoe.

The means for stopping the machine in case of a mis-stitch (see Figs. 13, 18, 22 and 26) is actuated by the relative positions of the main and auxiliary take-up members and comprise contact members 912 fixed in insulating material carried by the fulcrum shaft 878 by which the main take-up member 876 is operated. The auxiliary take-up member 884 is carried on the shaft 878 which 20 passes loosely through a hub portion 914 of the auxiliary take-up member. Also, extending from the hub 914 is an arm 916 carrying a double ended spring contact 918 separated from the end of the arm by insulating material. The two contact 25 members 912 are provided with arcuate surfaces for forming a rubbing contact with spring supported brushes 920 insulated from the frame of the machine and connected to wires 922 and 924, respectively. The contact members 912 are fastened with radial shoulders 926 to which are attached contact disks 928 of suitable refractory metal to cooperate with corresponding disks on the two ends of the spring contact 918. Movements of the contact 918 and the contact members 912 together, as shown in Figure 22, complete the connections from wire 922, through the corresponding brush 920, the contact member 912, the spring contact 918, the other member 912 and back through the wire 924 by the corresponding 40 brush 920. The completion of the circuit through these connections actuates electrical apparatus hereinafter described to stop the machine without actuating the thread cutter or throwing the jack out of operative position in the machine.

The main take-up member is operated from the main sewing cam shaft by oscillation of fulcrum shaft 878 (see Fig. 23) which shaft has suitable bearings in the sewing machine frame. The shaft is oscillated by a gear segment 930 fixed to the shaft 878 and meshing with a segment 932 fulcrumed loosely on a shaft 934 and provided with an arm 936 extending rearwardly and upwardly, carrying a follower for engaging a cam on the sewing cam shaft. The auxiliary take-up member 884 (see Fig. 26) is operated in one direction by the tension of the thread and in the other direction by a spring 938, stretched between a right angle arm 940 extending from the hub of the auxiliary take-up member and the frame of the machine. A stop is provided for the auxiliary take-up member in the form of an adjustable abutment screw 942 threaded into the sewing frame for preventing extreme movement of the auxiliary take-up member during the operation of the machine. 60 The abutment screw is so adjusted that with the auxiliary take-up released to its extreme position under the action of spring 938, the contact members 912 operated by the main take-up will just contact with the double ended spring contact 918 operated by the auxiliary take-up at the extreme position occupied by the main take-up. The auxiliary take-up may strike the abutment screw 942 at any other point during the stitch-forming cycle of operations without completing 70 75 80 85 90 95 100 105 110 115 120 125 130 135 140 145 the circuit through the contacts. At the time when each stitch is set the thread extends in a substantially straight line between the stationary pulley 880 and the pulley 886 rotating loosely 5 on the fulcrum shaft 878, with the auxiliary take-up resting on this straight portion of thread. The thread is subject to the greatest tension at this time and the auxiliary take-up member is also in its most forward position. If breakage or slack 10 thread from other cause occurs at this time, the circuit between the contacts will be closed (see Fig. 22) and the machine brought to rest.

The electrical apparatus connected with contacts 912 for stopping the machine upon the occurrence of a mis-stitch is illustrated diagrammatically in Figure 13. The wires 922 and 924 connected to the brushes 920 are connected to one terminal of the low voltage winding of the transformer 456 and to a relay 944. The relay 944 is connected by a wire 946 to a stationary contact 948 positioned to be acted upon by a movable contact 950. The movable contact is connected to the other terminal of the low voltage winding of the transformer 456 by a wire 952. When the circuit is closed through contacts 948 and 950 and through the contacts 912 and 918, the relay 944 is energized, closing relay contacts 954 having a connection 956 to one side of the source of power 450. A connection 958 from the other side of the source of power 450 completes the circuit through a solenoid 960. Thus, when the coil circuit of the relay 944 is completed, the solenoid 960 will be energized to retract its armature 962. The solenoid 960 is bolted at 963 to the right-hand edge of the base of the machine, adjacent the V-notched end of the short lever 260 for actuating the control bar 262 (see Figs. 1, 2, 3, 5, 7, and 8). As will be remembered, operation of the control bar 262 by the lever 260 actuates mechanism to bring the machine to rest. The armature 962 of the solenoid 960 is pivotally connected to an eye bolt 964 threaded into a hooked member 966. The forward end of the hooked member is provided with a notch to cooperate with a detent 45 968 fixed to a shaft which is journalled in a bracket 970 extending from the base of the machine and attached to the frame of the solenoid. At the lower end of the shaft carrying the detent, an arm 971 acts on the notched end of the short 50 lever 260 to move it forwardly when the magnet 960 is energized and raise the control bar 262. Movement of the lever 260 moves the link 258 toward the rear of the machine. The connection between the link 258 and the lever 254 is a pin 55 and slot so that the slotted end of the link slides idly without actuating the lever 254 or moving the short lever 478 which positions the vertical rod 472 to strike the auxiliary clutch actuating lever 470. Since no movement of these levers 60 is produced, the auxiliary clutch for completing the movement of the jack and pattern cam shaft is not thrown into operation and the jack remains in operative position with the sewing mechanism, when the machine is stopped by energizing the 65 solenoid 960. As the armature 962 is retracted, a positioning pin 972 fixed in the bracket 970 and sliding in an oblique slot 974 in the hooked member 966 acts to throw the free end of the hooked member away from the end of the detent 70 968 to permit the lever 260 to return to its original position. When the solenoid is de-energized, a spring presses the armature 962 out of the coil and a spring 975 causes the hook member 966 to snap in front of the detent 968 ready for another operation. The detent is held in contact

with the lever 260 by a spring 977, so that the hook member will move into proper cooperative relation therewith.

The thread cutter is arranged to be actuated only at the end of the outseam, at which time the sewing mechanism has reached the breast line of the heel and the pattern cam shaft has substantially completed its rotation. To secure this result, the lever 246 operated by the block 244 on the pattern cam shaft is provided at its left hand end with a pivotal connection to a link 976 (see Figs. 3, 6, 23 and 30) pivotally connected at its forward end to a lever 978 fulcrumed on the bracket 893 at the rear of the sewing mechanism. The upper arm of the lever 978 is pivotally connected with a link 980 having its upper end pivoted to a lever 982. The lever 982 is fulcrumed at 984 on the sewing machine frame (see Fig. 17) and extends forwardly over the rear end of the pawl 746 which strikes the abutment 748 to release the thread cutting clutch for one revolution. The lever 246 is spring pressed toward the pattern cam shaft, causing the link 976 to be retained yieldingly in a rearward position and the pawl 746 to be held raised from engagement with the abutment 748 by the action of the lever 982 on the rear end of the pawl. In this position of the pawl, the thread cutting clutch cannot be actuated but when the pattern cam shaft has substantially completed its rotation, the block 244 acts to move the lever 246 and to release the pawl 746 from contact with the lever 982 through the connections described. The thread cutter clutch may thus be coupled to cut the thread and release the shoe from the stitch-forming devices only when the pattern cam shaft has nearly reached its stopping position.

Means is also provided for preventing the operation of the thread break solenoid 960 upon the occurrence of slack thread during the first few stitches on a new shoe and during the final movements of the machine. To this end the block 244 on the pattern cam shaft for operating the stop motion is arranged to strike the end of a lever 286 (see Figs. 3 and 13) fulcrumed at 988 on the frame of the machine and pivotally connected to a lever 990 by an intermediate link 992, extending through an opening in the casing of the base of the machine. The lever 990 is mounted to rock about a supporting shaft 994 40 50 fixed to a bracket 996 attached to the rear of the base and operates a second lever 1000, also pivoted on the shaft 994, through a spring 998 connecting lugs on the two levers and yieldingly holding a set screw 1002 mounted in the lug on the lever 990 in contact with the lug on lever 1000. The lever 1000 carries the insulated contact 950 and is normally held in a position in which the contact 950 engages the contact 948, insulated from the bracket 996 by a spring 1004 55 60 stretched between the lever 990 and the frame of the machine. The wires 946 and 952 are connected, respectively, to the contacts 948 and 950 and lead through an armored cable or other suitable conduit to the box 458 in which the various circuit connections are made. When the pattern cam shaft has rotated to the point where the block 244 strikes the pawl lever 508, the stop mechanism is set in operation in the usual manner by rocking the lever 246. During the final 70 movements of the pattern cam shaft the lever 986 is also moved rearwardly by the block 244, breaking the circuit to the relay 944 by separating the contacts 948 and 950. Should a thread break occur at this time and the contacts 912 75

and 918 be moved together the relay 944 will not be energized nor the armature 962 be retracted. The contacts 948 and 950 are caused to remain separated during the first few stitches on a new shoe by positioning the end of the lever 986 so that it will not be relieved from the block 244 immediately upon starting the machine. If the contacts 912 and 918 should come together during the first few initial stitches, on account 10 of slack thread produced by rotation of the tension wheel, the machine will not be stopped because the controlling circuit of solenoid 960 is maintained open by contacts 948 and 950.

The sewing devices of the machine are constructed and arranged to impart a continuous feeding movement to the work and to this end the work support and presser-foot are mounted upon a laterally sliding carriage or feed slide, and the needle and awl are also mounted upon 20 this carriage but, at certain times during the stitch-forming and work-feeding cycle, are moved in the line of feed independently of the carriage. The feed carriage and the construction by which the needle and awl are mounted in the carriage 25 and given an independent movement at certain times with relation to the carriage are similar in many respects to the construction disclosed in the patent to Laurence E. Topham, No. 1,679,753, dated August 7, 1928. The specific 30 construction and arrangement of many of the parts, however, is different from the construction disclosed in the Topham patent, and the stitch-forming and work feeding devices are timed in a different manner, the back feed of 35 the feed carriage taking place while the needle is in the work instead of while the awl is in the work, as in the Topham construction, and the awl being arranged to enter the work after the needle has withdrawn with its loop of thread 40 and to withdraw from the work before the loop is drawn into its final position in the seam to set the stitch. The laterally sliding feed carriage is indicated at 668 and is slidably supported by a rearwardly extended portion provided with a 45 slot engaging a block 1005 mounted on a rod 1006 fixed in the machine frame and by gudgeons 1008 extending in opposite directions from the carriage near its central part and having a sliding engagement with guideways in the machine 50 frame. The gudgeon extending from the right side of the carriage is connected at its end to the lower end of a fulcrum plate 1010 (see Fig. 35) by means of a screw 1012 and the central part of the fulcrum plate supports the presser- 55 foot fulcrum screw 666 threaded into the feed carriage. The upper end of the fulcrum plate carries the stud 676 on which the arm 674 for operating the thread cutter is mounted.

Feeding movements of the feed carriage are 60 produced by a connection to the gudgeon member 1008 extending from the left side of the feed carriage. For this purpose a pair of adjustable links 1016 (see Figs. 16, 21, 23, 24 and 35) are pivotally connected by a pin 1018 to the outer 65 end of the left hand gudgeon member. These links are provided with serrated surfaces to cooperate with correspondingly shaped surfaces of washers surrounding studs attached to the outer end of a lever 1020. Nuts on the studs hold 70 the washers in firm engagement with the adjusting links 1016 while the opposite ends of the studs are loosely journaled in the end of the lever 1020. The lever 1020 is fulcrumed on the frame of the machine by means of a bolt 1022 75 passing through a slot in the lever 1020 and

having a squared head slidably arranged in a dovetail guide block 1024. The guide block 1024 is clamped in a seat on the frame of the machine by an extending pin 1026 carrying a nut threaded on its end. The bolt 1022 is fixed with relation to the guide block 1024 by a U-shaped strap 1028 straddling the central part of the lever 1020 (see Fig. 21) and having its ends resting in grooves on the outer edges of the guide block. A sleeve 1030 rotates loosely on the bolt 1022 and 10 is clamped in adjusted position in the slot by a nut 1032 acting to thrust a collar at the lower end of the sleeve against the under side of the lever. The rearward end of the lever carries a follower 1034 cooperating with a cam on the 15 sewing cam shaft. By loosening the nuts on the bolt 1022 and the sleeve 1030, the position of the pin 1022 may be moved forwardly or rearwardly of the machine without moving the lever 1020, thus varying the proportionate length of the 20 operating and operated arms of the lever and, consequently, the movement imparted to the feed carriage. Markings on the guide block 1024 indicate, according to the adjustment of the fulcrum bolt 1022, the number of stitches per inch corresponding to that adjustment. During the adjustment of the fulcrum bolt 1022 of the feed slide operating lever, the lever is held in position by a screw 1036 threaded into the end of the left hand gudgeon member of the feed carriage 30 through an opening in the forward end of the feed lever. The lever is maintained in contact with the screw 1036 by a spring 1038 interposed between the side of screw 1036 and the end of a screw 1040 to permit slight independent movement between the two parts during normal operation of the machine.

The forward end of the feed carriage supports a threaded bearing 1042 (see Figs. 25, 35, 38 and 39) carrying a threaded end of a stud 1044 upon 40 which the needle and awl segments, indicated at 1046 and 1048, respectively, are rotatably mounted. The stud 1044 is oscillated by a segment 1050 fixed to the stud, rotation of which produces lateral feeding movement of the needle and awl independently of the movement of the feed carriage 668. The needle and awl segments are actuated by corresponding segments carried on arms 1051 and 1053 fulcrumed on the machine and provided with follower members engaging 50 suitably shaped cams on the sewing cam shaft. The segment 1050 for producing the independent feeding movements of the needle and awl is actuated by a segment arm 1052 fixed to one end of a shaft 1054 journalled in the feed carriage. The 55 other end of the shaft 1054 is provided with an upwardly curved arm 1056 formed with a slot engaged by a bolt 1058. The arm is operated through a link 1060 having a ball and socket connection at one end with the bolt 1058 and a 60 similar connection at the other end with a bolt 1062 secured to a bell crank 1064. The bell crank is rotatably mounted on a shaft 1066 fixed in the main frame of the machine and is operated by a follower 1068 engaging a cam on the 65 sewing cam shaft. Feeding movements of the feed carriage with relation to the bell crank 1064 do not interfere with the operation of the arm 1056 on account of the universal action of the ball and socket joints. Adjustment for length 70 of independent feeding movement of the stud 1044 is accomplished by changing the position of the bolt 1058 in the slot on the arm 1056. The needle and awl carrying stud 1044 is supported at its right end, as viewed from the front of 75

the machine, by a bearing 1070 formed in the bracket 682 in which the end of the stud is freely slideable and rotatable.

An adjustment for taking up lost motion between the needle and awl carrying stud and the feed carriage comprises an internally threaded collar 1072 (see Figs. 38 and 39) engaging the thread of the stud. The collar is contained in a recess at one side of the threaded bearing 1042 on the feed slide and is held in the recess by an external thread on the collar engaging corresponding threads within the bearing. The external thread of the collar and the internal thread cooperating with the needle and awl stud are formed with different pitches so that rotation of the collar will grip the thread of the stud more closely between the respective threads of the bearing and collar. The collar may be fixed in any angular relation with respect to the bearing by means of screws 1074 threaded through the bearing and having their inner ends engaging notches formed in the edge of the collar.

On account of the frictional engagement between the other sewing devices and the work, the needle may be subjected to considerable strain during its independent feeding movement. In order to reduce this strain, the movements of the looper 550 with relation to the other movements of the stitch-forming devices has been speeded up so that a loop of thread will be laid in the barb of the needle and the looper will be moved in the direction of feed and toward the center of curvature of the needle before the feeding movement of the needle is completed. The tension on the thread, thus exerts a force to counteract in a large degree the effort applied to the needle on account of the frictional drag between the work and the other stitch-forming devices during the back feed of the feed carriage.

The machine is also provided with a channelling or fudge knife operating to form a groove in advance of the stitching devices so that the stitches may be set below the surface throughout a portion of the outseam. The knife, indicated at 1082, (see Figs. 16, 22 and 25) is projected upwardly through the work table and operated in timed relation with the other stitch forming movements. The knife is sharpened with an edge acting against the direction of feed and oscillates, to cut the work, about a stub shaft 1084. The shaft is carried by a block 1086 having flanges fitting an obliquely arranged dove-tail guide 1088 fixed to the feed carriage. The knife 1082 is actuated through its cutting movements by means of an arm 1090 extending from a lever having a clamp portion 1092 carrying the knife and a hub surrounding the stub shaft 1084. The arm 1090 is connected to a link 1096 (Fig. 35) having a ball and socket connection with the arm at its lower end and a similar connection at its upper end with a screw 1098, threaded into a lug 1100 (Fig. 25). The lug extends from the shaft 1054 which is rocked to move the needle stud through its independent feeding movements. The screw 1098 may be so adjusted in the lug 1100 that the movement imparted to the upper end of the channelling knife 1082 corresponds very closely with the feeding movements of the needle, maintaining a substantially uniform displacement of the knife from the plane of the needle. The knife is actuated intermittently to cut the work in the line of feed by these connections, in unison with the reverse feeding movements of the needle so that, while the needle is engaging the work and operating in the direction of feed, and the presser-foot

has released the work, the knife is moving with the work, and no cutting action takes place. Movement of the knife against the work occurs after the presser-foot has again clamped the work firmly against the work support and the needle is disengaged from the work and being back fed. The advantages of so timing the movements are obvious, since cutting action of the knife takes place only when the work is securely clamped and not in such a way as to impose an unnecessary strain on the needle or awl.

The knife 1082 operates to engage the work only about the forepart of the outsole and is disengaged from the work by lowering the knife bodily with its supporting lever along the instep portion of the shoe. For this purpose the block 1086 is constructed with a depending finger 1102 engaging at its lower end a cam 1104 carried on a shaft 1106. The block 1086 is yieldingly maintained in a lowered position with respect to the guide 1088 by a spring 1108 stretched between a pin on the finger 1102 and the end of the shaft 1106 on which the cam is mounted. The shaft 1106 passes through a sleeve 1110 (see Figs. 16 and 18) journalled in a boss formed on the lower part of the bracket 682 forming part of the machine frame and the sleeve is attached at one end to a slotted arm 1112. The sleeve 1110 is operatively connected to the shaft 1106 by a block 1116 and bolts 1114 slideable in the block, there being indentations in the sides of the bolts to accommodate the sleeve and the shaft so that, when tightened, the bolts will bind against the sleeve and shaft, respectively. The slotted arm 1112 is operated by a link 1118 adjustably pivoted on the arm by means of a bolt 1120. The lower end of the link 1118 is connected by means of a universal joint 1122 (see Figs. 7 and 8) at one side of a hub member 1123 fixed to a short inclined shaft 1124, fulcrumed on the frame of the machine. Oscillation of the hub member moves the link 1118 in a vertical direction to rock the cam shaft 1106 and raise and lower the channelling knife by sliding the block 1086 within the dove-tail guide in which it is mounted. The hub member is oscillated from a cam on the pattern cam shaft so that the knife will be raised into operative position to engage the shoe about the forepart and be lowered to a position disengaged from the shoe along the remainder of the outseam. The connection to the cam shaft consists of an arm 1126 (see Figs. 1, 2, and 3) extending upwardly from the hub member. The upper end of the arm is provided with a clevis 1128 having a pivotal connection to a link 1130. The link 1130 extends toward the right side of the machine and is connected by means of a universal joint with an arm on a vertical shaft 1132 having upper and lower bearings in the frame of the machine. The lower end of the shaft 1132 is operated through another arm connected to a bell crank 1134 by means of a link 1136. The other arm of the bell crank is provided with a follower cooperating with a cam on the pattern cam shaft.

The distance between the edge of the sole and the line of stitching is determined by the movement of an edge gage of usual construction, indicated at 1138 (see Fig. 18). The edge gage is operated by the same connections which operate the channel knife, to move the edge of the shoe closer to or further from the line of operation of the stitch-forming devices. The edge gage is mounted on an arm 1140 pivoted on a screw 1142 carried by the stationary bracket 682. The arm 1140 is yieldingly moved toward the rear of the machine by a spring 1144 stretched between the

arm and the frame of the machine. The edge gage is moved forwardly to suitably position the edge of the shoe, through the action of a cam surface 1146 (see Figs. 16 and 25) formed on the hub of the slotted operating arm 1112. The arm 1140 is provided with an arm 1148 carrying a set screw 1150 which bears against the cam surface 1146. Through these connections the slotted arm 1112 for operating the fudge knife also operates the edge gage at the proper time. The cams 1104 and 1146 are adjustable with relation to each other by loosening the bolts 1114 and the amount of simultaneous movement imparted to both the edge gage and the knife is adjustable by changing the position of the bolt 1120 in the slot of the arm 1112. The cams 1104 and 1146 may be adjusted by this means to render either or both devices inoperative, as desired.

To permit the operator to release, at will, the presser-foot from its gripping position on the edge of the shoe, the spring pressed locking wedge block 834 which, during its upward movement acts to move and lock the presser-foot against the work, is connected by means of a screw 1180 to a link 1182 (see Figs. 7 and 20). This link is pivotally connected at its lower end to a U-shaped lever 1184, fulcrumed on a screw 1186 passing through a bifurcated portion of the lever surrounding a lug on the frame of the machine. The lever is operated by a hand lever 1188 pivoted loosely on the screw 1186 and acted upon by a coil spring 1190 to swing it rearwardly of the machine. The hand lever is moved forwardly to release the presser-foot and in so doing, strikes a pin 1192 on the lever 1184, depressing the lever 1184 and the locking wedge block 834 which is connected to it.

The thread measuring mechanism of the machine comprises means for drawing, intermittently from the shuttle, a predetermined supply of thread and locking the thread after the measuring movement at the point where it leaves the shuttle. Prior to the action of the main take-up in setting a stitch a supply of needle thread is drawn from a tension wheel, lacking slightly in amount that necessary to complete a stitch, and the main take-up in setting the stitch against the locked bobbin thread withdraws a further amount of needle thread from the thread tension wheel under a uniform tension and at a point in the path of movement of the main take-up where the take-up is moving at a comparatively slow rate, so that a sudden rotation is not imparted to the thread tension wheel to cause it to overrun or otherwise non-uniformly affect the stitching.

The shuttle 548, of the rotary hook type, (see Figs. 20 and 26 to 29) is rotated continuously by a bevel gear 1202 driven through a shaft 1204 and a helical gear 1206 meshing with a corresponding gear 1208 on the sewing cam shaft. The gear 1202 meshes with gear teeth 1210 formed on a part of the shuttle enclosed in a protecting casing 1212. The shuttle is mounted in a well known manner in a split annular bearing plate 1214 secured to an extension 1216 from the sewing frame of the machine. The supply of locking thread is retained upon a bobbin 1218 arranged concentrically with the axis of rotation of the shuttle by a split pin 1220 supported at the center of a bobbin case 1222 mounted within the shuttle 548. The bobbin case is supported in the shuttle by a collar 1224 extending from the bobbin case and sliding in a groove in the shuttle. The bobbin case is held against rotary movement by cam operated dogs 1228 slidably ar-

ranged in passages formed in the casing 1212 and movable in a direction parallel to the axis of rotation of the shuttle. The lower ends of the dogs engage notches in the upper edge of the bobbin case and are alternately raised from the notches against the action of a spring 1230 by a cam shaped ring 1232 extending inwardly from the shuttle. The pins 1228 are provided with shoulders for engagement with the cam ring 1232. The spring 1230 is constructed in a circular shape 10 and provided with loop portions surrounding pins 1234 (see Fig. 16) extending radially from lugs on the casing 1212. As the shuttle is rotated, the pins 1228 are reciprocated by the cam ring, raising first one and then the other from the notches 15 in the bobbin case so that the loop of needle thread may pass unimpeded about the bobbin case. The bobbin 1218 is retained on the split pin 1220 by a slight restriction at one end of the opening in the bobbin, cooperating with a groove 20 at the outer end of the pin. Splitting the pin provides a certain amount of resiliency so that the bobbin may snap into position. Overrunning of the bobbin is prevented by a circumferential leaf spring 1236 (see Fig. 29) secured at one end 25 to the outside of the bobbin case. The other end of the spring extends through the side of the bobbin case and rests against the outside flanges of the bobbin. A flange 1238 extending from the spring assists in retaining the bobbin in proper 30 axial position.

The bobbin thread lock is carried by the bobbin case and comprises a curved member 1240 fitted within a recess in the side of the bobbin case 1222. The member 1240 is mounted for pivotal 35 movement about a pin 1242 fixed in the bobbin case and is pressed outwardly at one end in a radial direction by a spring 1244 held in place by a pin 1246. The opposite end of the curved member is constructed with a locking lug 1248 forming a gripping jaw arranged to bite a portion of the thread against a cooperating jaw on the bobbin case as the thread passes from the bobbin. The bobbin case is provided with an opening 1252 through which the thread leads from the bobbin 45 and the extreme end 1250 of the curved lock member is bifurcated to guide the thread as it leaves the bobbin case. As the shuttle 548 is rotated the thread is released from the grip of the locking lug 1248 by a roll 1254 rotating on a 50 screw 1256 threaded in the shuttle. The roll 1254 is positioned in suitable angular relation on the shuttle to compress the spring and release the locking lug at the proper times to allow withdrawal of thread for each succeeding stitch. 55

The thread is measured from the shuttle by a thread measuring member 1258 (see Figs. 16, 26, 36 and 37) formed with a pair of manipulating fingers 1260 and 1262 and a supporting shaft portion 1264. The thread measuring member is retained in a chuck 1266 carried at the end of a shaft 1268 inclined forwardly and directed downwardly and rotatable in bearings formed in a tubular extension 1270 from the frame of the machine. The shaft 1268 is constructed and arranged to move the thread measuring member into and out of the path taken by the locking thread between the bobbin thread case and the work. The finger 1260 on the thread measuring member is displaced from the center of rotation 60 of the shaft 1268 a suitable distance to withdraw thread from the shuttle when rotated in the direction of the arrow in Fig. 37. The finger 1262 of the thread measuring member is positioned slightly to one side of the center of rotation 70 75

tion of the shaft 1268 and is so arranged that the finger, as it engages the thread has substantially no tendency to draw the thread backwardly from the work. The shaft 1268 is slideable as well as rotatable so that the thread measuring member may be moved forwardly to engage and measure the thread and be retracted to disengage the thread. While moved to retracted position the thread measuring member is protected by a shield 1272 which is fixed upon the end of the tubular extension 1270 and partially surrounds the member. When the thread measuring member is retracted within the shield, interference of the extending fingers with the needle thread loop, as it is passed around the bobbin case by the shuttle, is prevented.

The locking thread measuring member and the shaft 1268 upon which it is mounted are rotated by an elongated pinion 1274 (see Fig. 16) on the shaft engaged by a rack member 1276 slideable in a guideway 1278 formed in the sewing frame. Longitudinal sliding movements of the shaft 1268 are produced by the action of a helically threaded portion 1280 formed at the upper end of the shaft 25 and a correspondingly threaded nut member 1282 (see Figs. 5 and 23) positioned in alignment with the shaft by a screw 1284 extending through a slot formed in a tab 1286 of the nut member 1282 into the extension 1270 of the frame. In order to rotate the shaft 1268 and the thread measuring member to engage and measure the thread in timed relation to the movements of the other stitch-forming devices, a connecting link 1288 is attached to the rack member 1276 with a universal joint and to the end of a bolt 1290 with a corresponding connection. The bolt 1290 is adjustable along a slot formed in an arm 1291 extending from a hub 1292 rotatably mounted on the shaft 934 about which the take-up gear segment operates. The hub 1292 carries a gear segment 1294 meshing with a corresponding segment formed on an arm 1296. The arm 1296 is fulcrumed loosely on a shaft 1298 at the rear of the machine and is provided with a follower 1300 engaging a cam on the sewing cam shaft. Reciprocation of the rack 1276 produces rotating and sliding movements of the thread measuring member through the connections described. The stroke imparted to the rock shaft may be varied 50 in length by changing the position of the bolt 1290 in the slot of the arm 1291. The angular position of the nut 1282 may be adjusted by loosening the screw 1284 and the thread measuring member is adjustable in the collet 1266 55 to cause it to operate in the proper path of movement.

The movements of the thread measuring member are timed with relation to the other stitch forming devices so that the thread will be held 60 by the thread measuring member during the interval between the disengagement of the needle from the work and the passing of the loop of needle thread about the thread case by the shuttle. The thread measuring member acts to measure the thread just after the previously formed 65 stitch is set and the main take-up is at its lowermost position. At this time, the needle thread is subject to a maximum tension and displacement of a previously completed stitch by the 70 action of the thread measuring member is prevented. During the rotation of the shuttle after the thread measuring member has operated to measure the locking thread, the inner edge 1306 of the shuttle diverts a portion of the locking 75 thread from its normal path and tends to with-

draw thread from the work. In order to prevent this undesired movement of the thread, the thread measuring member releases the thread by the proper amount to permit the thread to clear the edge of the shuttle. The thread measuring member subsequently takes up the slack 5 to prevent displacement or entanglement of the thread until a new loop of needle thread is withdrawn from the work.

The needle thread measuring mechanism comprises a reciprocating forked rod 1310 (see Fig. 23) pivotally supported at its upper end on an arm 1312. The arm 1312 is pivotally mounted on the rearward end of a lever 1314 fixed on the shaft 1298. The forked rod 1310 is slideable at 15 its lower end in a guide 1316 extending from the bracket 893 at the rear of the machine and engages the thread with its forked end between the one-way gripper 888 and the tension wheel, so that, as the rod 1310 diverts the thread from 20 its normal path, the gripper acts to prevent backward movement of the thread and the tension wheel 890 is rotated according to the amount of thread measured. Rotation of the thread tension wheel 890 is resisted by a brake shoe 1320 25 (see Figs. 23, 31, 32 and 33) pivotally mounted on a brake arm 1322. The brake arm 1322 is pivoted at 1324 to the bracket 893 in which the tension wheel shaft 892 is journaled and the rearwardly extending end of the brake arm is pressed 30 downwardly by a spring 1328 carried on a vertical bolt 1330. The lower end of the bolt 1330 is formed with an eye pivoted on a pin 1332 carried on the bracket 893 and the spring 1328 is retained on the bolt by an adjustable thumb nut 35 1334 for varying the pressure on the brake shoe 1320. A brake drum 1335 is secured to the shaft 892 which carries the thread tension wheel 890. Pressure of the brake shoe 1320 on the drum 1335 produces a uniform frictional drag against the 40 rotation of the tension wheel, according to the setting of the thumb nut 1334.

The forked rod 1310, for measuring thread from the tension wheel, and the brake arm 1322 are operated in timed relation to the other stitch-forming devices through connections to a cam on the sewing cam shaft, and the measuring movement of the forked rod is controlled by connections to the presser-foot. The shaft 1298 is oscillated by a cam follower arm 1336 cooperating with a cam on the sewing cam shaft (see Fig. 23). At an intermediate part of the arm 1312 a pivotal connection 1338 is made to a link 1340, the lower end of which is pivotally connected to an arm 1342 fixed to a rock shaft 1344 journalled 50 in the sewing frame. The opposite end of the shaft 1344 carries an arm 1346 having at its upper end a universal joint connection to a link 1348 extending toward the front of the machine and coupled by means of a similar connection to an 60 upwardly extending arm 1350 (see Fig. 20) of the presser-foot 546. The pivotal connection 1338 between the arm 1312 and the link 1340 forms a fulcrum about which the lever 1312 swings in depressing the rod 1310 to engage the 65 needle thread, and the connections to the presser-foot, above described, change the position of this fulcrum in accordance with variations in thickness of material between the presser-foot and the work support. The measuring operation of 70 the forked rod 1310 takes place while the presser-foot is clamped in engagement with the work, so that the arm 1312 is rocked about the pivot 1338 by the operating lever 1314 while the presser-foot is held stationary. With thick materials be- 75

tween the presser-foot and work support, the pivot 1338 is lowered, causing the forked rod 1310 to measure off more thread. Thread is measured by the forked rod during upward movement of the pivot 1325 on the lever 1314.

The lever 1314 is provided with a rearward extension 1352 for releasing the brake during the thread measuring operation. The brake arm 1322 is operated through a stud 1354 extending from a central part of the brake arm. The stud is engaged by a cam surface 1356 on a sector 1358 fixed to a short shaft 1360 fulcrumed on the bracket 893. The shaft 1360 is rocked by the lever 1314 through a connecting link 1362 pivotally connected at its upper end to the extension 1352 on the lever 1314 and at its lower end to an arm 1364 fixed to the shaft 1360. Upward movement of the operating lever 1314 swings the sector 1358 to raise the brake arm 1322 against the action of the spring 1328 and the brake shoe is then released from the brake drum on the thread tension shaft. This permits free movement of the tension wheel except for a slight drag to prevent over-running so that the proper amount of thread will be measured for each stitch.

The operation of the needle thread measuring mechanism is so timed with relation to the other thread handling devices that, during the last cycle of operations, as the machine stops, thread is pulled from the supply prior to the operation of the thread cutter. On account of the mis-looping of the needle, no thread is drawn through the work by the needle during its final retracting stroke, and this thread together with the thread drawn from the supply by the thread measuring devices provides a sufficient length of thread to extend beyond the work table as the shoe is moved away from the stitch-forming devices by the outward movement of the jack.

In this connection it is to be noted that the mechanism for measuring the locking thread also acts just prior to the operation of the thread cutter and prior to the point in the cycle of operations at which the machine stops. A supply of locking thread is thus provided for starting a new seam sufficient to insure its engagement by the needle loop during the formation of the first stitch.

The needle guide, indicated at 1366, operates to shield the barb of the needle against interference with the locking thread as it is withdrawn from the work, as shown in Fig. 26. The needle guide is mounted to oscillate freely about the stud 1044 which carries the needle and awl segments and is positively actuated by gear teeth 1368 (see Fig. 18) formed on the hub of the needle guide. The teeth 1368 mesh with a gear segment 1370 pivoted on a stub shaft 1372. The segment is operated by a vertical link 1374 pivotally connected at its lower end with the segment and at its upper end to an arm 1376 (see Figs. 16 and 23) fixed to the horizontal shaft 756. The shaft 756 is oscillated in its bearings in the sewing frame by a gear segment 1378 mounted for rotation upon the fixed shaft 715 and meshed with a corresponding segment 1380 fixed to the shaft 756. The segment 1378 is operated through an integral arm 1382 provided with a follower engaging a cam on the sewing cam shaft. The cam is so constructed that the needle guide is operated through the connections described, in timed relation with the operation of the needle as it moves upwardly from the work. The needle thread retained on the barb of the needle is released by movement of the

guide away from the end of the needle just before the thread is passed to the shuttle and the barb is covered again by the guide immediately afterward.

A thread lifter in the usual form, indicated 5 at 1386 (see Figs. 17 and 25) is mounted for movement about a short shaft 1388 journalled on an upward extension of the feed slide 668. The thread lifter is operated by a cam on the sewing cam shaft which acts upon a follower arm 1390 10 fulcrumed loosely on the shaft 756 and provided with a downwardly extending segment 1392 meshing with a corresponding segment 1394 fixed to the shaft 1388 which operates the thread lifter.

Means for controlling the thread below the 15 work support comprises a thread finger of well known construction, indicated at 1398 (see Fig. 26) and is mounted to slide horizontally in a guideway 1400 in the feed carriage. The thread finger is operated by a curved vertical arm 1402 20 terminating in a gear segment 1404, engaging rack teeth 1406 on the thread finger. The arm 1402 is mounted to rotate loosely about the shaft 775 and is actuated by a rearwardly extending follower arm and a cam on the sewing cam shaft. 25

Certain features of the machine herein disclosed relating more particularly to the power starting mechanism and to the jack supporting and actuating structure form the subject-matter of divisional application Serial No. 19,211 filed 30 May 1, 1935, and certain features of the machine herein disclosed relating to the means for stopping the machine upon occurrence of a mis-stitch form the subject-matter of divisional application Serial No. 8,863 filed March 1, 1935. 35

The nature and scope of the present invention having been indicated and a machine embodying the several features having been specifically described, what is claimed is:

1. A sewing machine having, in combination, 40 stitch-forming devices, an operating shaft and connections for actuating said devices, a power driver, a power actuated auxiliary mechanism acting when thrown into operation to connect the operating shaft to the driver and to draw 45 thread from the supply sufficient to provide effective initial operation of the stitch-forming devices, and a manually actuatable member for controlling said auxiliary mechanism.

2. A shoe machine having, in combination, 50 means for operating upon a shoe including a shoe clamping presser-foot, a main driver for the machine, a clutch having driving and driven parts for connecting said operating means with the main driver, apparatus driven through the clutch 55 for disengaging the clutch parts subsequently to a predetermined operation of the machine, auxiliary mechanism driven by said main driver for causing the engagement of the clutch parts and for causing said presser-foot to move against a shoe, and a manually actuatable member for controlling said auxiliary mechanism.

3. A shoe sewing machine having, in combination, 55 stitch-forming devices including a hook needle and looper shiftable to and from looping position, a main driver for the machine, a clutch having driving and driven parts for connecting said stitch-forming devices with the main driver, apparatus driven through the clutch for disengaging the clutch parts subsequently to a predetermined operation of the stitch-forming devices, auxiliary mechanism driven by the main driver for causing the engagement of the clutch parts and for shifting said looper to looping position, 70 75

and a manually actuatable member for controlling said auxiliary mechanism.

4. A shoe sewing machine having, in combination, stitch-forming and thread handling devices including a thread cutter arranged to sever the thread and a thread pull-off device, apparatus for stopping the machine and operating the cutter to sever the thread, a main driver for the machine, a main clutch having driving and driven parts between the main driver and the machine, auxiliary mechanism associated with the main driver for effecting engagement between the main clutch parts and for actuating the thread pull-off to furnish an extra supply of thread to the stitch-forming devices, and a manual member for coupling said mechanism to the main driver to engage the clutch parts.

5. A sewing machine having, in combination, stitch-forming and thread handling devices including a thread cutter arranged to sever the thread close to the work and a thread pull-off device, means for holding the work comprising a work support and a presser-foot movable to and from said work support, apparatus for stopping the machine, operating the thread cutter and moving the presser-foot, a main driver for the machine, a main clutch having driving and driven parts between the main driver and the machine, auxiliary mechanism driven by the main driver for effecting engagement between the main clutch parts for starting the machine in operation and for actuating the thread pull-off to furnish an extra supply of thread to the stitch-forming devices, and a manual member for controlling said mechanism.

6. A shoe machine having, in combination, stitch-forming devices including a thread pull-off device to measure off an extra supply of thread sufficient to insure effective initial operation of the stitch-forming devices, a shoe supporting jack, mechanism for changing the relative positions of the stitch-forming devices and the jack to present the shoe properly to the stitch-forming devices as the point of operation is transferred about the shoe and to move the jack away from the stitch-forming devices upon completion of the seam, and mechanism operating subsequent to movement of the jack away from the stitch-forming devices and prior to initial operation of the stitch-forming devices on a new shoe for actuating the thread pull-off device to measure off said extra supply of thread.

7. A shoe machine having, in combination, stitch-forming devices including a thread pull-off to measure off an extra supply of thread sufficient to insure effective initial operation of the stitch-forming devices, a shoe supporting jack, mechanism for changing the relative positions of the stitch-forming devices and the jack to present the shoe properly to the stitch-forming devices as the point of operation is transferred about the shoe and to move the jack away from the stitch-forming devices upon completion of the seam, and mechanism operating subsequent to return movement of the jack into operative relation to the stitch-forming devices and prior to initial operation of the stitch-forming devices on a new shoe for actuating the thread pull-off to measure said thread.

70 8. A sewing machine having, in combination, stitch-forming devices including a work clamping presser-foot, a main driving shaft for operating said stitch-forming devices, a power driven mechanism acting when thrown into operation to cause said foot to move into clamping engagement with

the work and subsequently to cause the main driving shaft to be thrown into operation, and a manually actuatable member for controlling said power driven mechanism.

9. A shoe sewing machine having, in combination, stitch-forming devices, a work clamping presser-foot, a shoe supporting jack, mechanism for relatively actuating the stitch-forming devices and the jack to transfer the point of operation about the shoe, a driver for the machine, a main operating shaft for actuating the stitch-forming devices, presser-foot and jack during each stitch-forming cycle of operations of the machine, auxiliary driving shafts for effecting final movement of the presser-foot and jack to release the shoe and move the jack out of engaging position with said stitch-forming devices, and independent clutches for coupling the respective shafts to said driver.

10. A shoe sewing machine having, in combination, stitch-forming devices including a work clamping presser-foot for gripping the portion of a shoe engaged by the stitch-forming devices, a driver for the machine, a main operating shaft for actuating the stitch-forming devices and for actuating the presser-foot to release and grip the shoe during each stitch-forming cycle of operations, an auxiliary driving shaft and connections for effecting final movement of the presser-foot to release the shoe, and independent clutches for coupling said shafts to said driver.

11. A sewing machine having, in combination, stitch-forming devices, a cam shaft and suitable connections for actuating said stitch-forming devices, a stop mechanism acting, when thrown into operation, to bring the machine to rest, a thread cutter, power driven cutter actuating mechanism, and mechanism actuated by the sewing cam shaft and rendered operative by the stopping mechanism for throwing said cutter actuating mechanism into operation.

12. A sewing machine having, in combination, stitch-forming devices, a cam shaft and suitable connections for actuating said stitch-forming devices, a thread cutter, a power driven thread cutter actuating mechanism, a clutch for throwing in said mechanism, and mechanism actuated by the sewing cam shaft and rendered operative in stopping the machine for actuating the clutch.

13. A sewing machine having, in combination, stitch-forming devices, a thread cutter, a shoe supporting jack, a pattern cam shaft and suitable connections for relatively actuating the stitch-forming devices and the jack to transfer the point of operation of the stitch-forming devices along the shoe, power driven cutter actuating mechanism, mechanism actuated by the sewing cam shaft and rendered operative in stopping the machine for throwing said cutter actuating mechanism into operation, and means controlled by the pattern cam shaft for preventing the throwing into operation of the cutter actuating mechanism prior to the completion of the seam.

14. A sewing machine having, in combination, stitch-forming devices, a thread cutter, a shoe supporting jack, a pattern cam shaft and suitable connections for relatively actuating the stitch-forming devices and the jack to transfer the point of operation of the stitch-forming devices along the shoe, mechanism for actuating the thread cutter upon stopping the machine, and means controlled by the pattern cam shaft for preventing actuation of the thread cutter prior to the completion of the seam.

15. A sewing machine having, in combination, stitch-forming devices, a thread cutter, a shoe supporting jack, mechanism for relatively actuating the stitch-forming devices and the jack to transfer the point of operation of the stitch-forming devices along the shoe, a driver for the machine, a main operating shaft for actuating the stitch-forming devices, an auxiliary driving shaft for operating the thread cutter, a main clutch for coupling the main shaft to the driver, means acting on said main clutch and effective upon the completion of a seam or upon a mis-stitch prior to the completion of the seam to disconnect the main shaft from the driver, a secondary clutch for coupling the auxiliary shaft and driver, mechanism for operating said secondary clutch to connect the auxiliary shaft to said main driver upon disconnection of said main shaft and driver through the main clutch, and means for rendering said mechanism inoperative to cause rotation of said auxiliary shaft when said main clutch is operated upon a mis-stitch. 5
16. An outsole shoe sewing machine having, in combination, a work support, a presser-foot movable toward and from the work support to clamp the projecting edge of the sole of a shoe against the work support, lockstitch forming devices constructed and arranged to sew the outseam of the shoe, thread cutting mechanism mounted on the machine, and means for actuating said mechanism upon stopping the machine to cut both threads on the presser-foot side of the work. 10
17. An outsole shoe sewing machine having, in combination, a work support, a presser-foot movable toward and from the work support to clamp the projecting edge of the sole of a shoe against the work support, lockstitch forming devices constructed and arranged to sew the outseam of the shoe, a thread cutter mounted to move toward and from the work support as the work varies in thickness, and means for actuating the cutter upon stopping the machine to sever both threads on the presser-foot side of the work. 15
18. An outsole shoe sewing machine having, in combination, a work support, a presser-foot movable toward and from the work support to clamp the projecting edge of the sole of a shoe against the work support, lockstitch forming devices constructed and arranged to sew the outseam of the shoe, a thread cutter mounted to move with the presser-foot toward and from the work support, and means for actuating the cutter upon stopping the machine to cut both threads. 20
19. An outsole shoe sewing machine having, in combination, shoe supporting and guiding devices, comprising a work support and a presser-foot arranged to receive between them the projecting edge of the sole of a shoe, lockstitch forming devices constructed and arranged to sew the outseam of the shoe, a knife edged member movable on the machine for severing both threads at the completion of the outseam, and means for thrusting the knife member across the paths of said threads next the tread surface of said sole. 25
20. An outsole shoe sewing machine having, in combination, shoe supporting and guiding devices, comprising a work support and a presser-foot arranged to receive between them the projecting edge of the sole of a shoe, lockstitch forming devices constructed and arranged to sew the outseam of the shoe, a knife edged member movable on the machine for severing the thread laying along one surface of the sole, and means for actuating the knife across the path of said thread 30 in contact with the shoe sole. 30
21. An outsole shoe sewing machine having, in combination, lockstitch forming devices, a shoe supporting jack, mechanism for relatively actuating the stitch-forming devices and the jack to transfer the point of operation about the shoe, automatically actuated and controlled mechanism for stopping the stitch-forming devices at a pre-determined point in the sewing operation, a knife edged member movably mounted on the machine for severing both threads, and means rendered operative by said stopping mechanism for thrusting the knife member across the path of said threads next the tread surface of said sole upon operating the stop mechanism at the completion of the sewing operation. 35
22. An outsole shoe sewing machine having, in combination, shoe supporting and guiding devices, comprising a work support and a presser-foot arranged to receive between them the projecting edge of the sole of a lasted shoe, means for supplying needle and locking threads, stitch-forming devices adapted to pass the locking thread through a loop of needle thread and set the needle loop within the shoe sole, a thread cutter mounted on the machine for cutting movement at one side of the shoe sole, and means operating after setting of the final stitch for actuating said cutter to sever a needle loop and a straight portion of the locking thread at the end of the outseam. 40
23. An outsole shoe sewing machine having, in combination, shoe supporting and guiding devices comprising a work support and presser-foot arranged to receive between them the projecting edge of the sole of a lasted shoe, lock-stitch forming devices constructed and arranged to sew the outseam of the shoe and a knife edged member acting to form an incision in the tread surface of the shoe and to sever both threads at the completion of the outseam. 45
24. A machine for sewing shoes having, in combination, stitch-forming devices, a shoe supporting jack, mechanism for relatively actuating the stitch-forming devices and the jack to transfer the point of operation about the shoe and a thread cutting knife acting to form an incision in the shoe and to sever the thread beneath the tread surface upon completion of the outseam. 50
25. A machine for sewing shoes having, in combination, lockstitch forming devices, a shoe supporting jack, mechanism for relatively actuating the stitch-forming devices and the jack to transfer the point of operation about the shoe, a knife acting against the tread surface of the shoe to sever the thread, and mechanism for actuating said knife upon completion of the seam. 55
26. A machine for sewing shoes having, in combination, stitching devices for forming a lock-stitch seam, a shoe supporting jack, mechanism for relatively actuating the stitching devices and the jack to transfer the point of operation about the shoe, a thread cutting knife acting against the tread surface of a shoe to sever one thread and to cut below the tread surface to sever another thread, and operating means for projecting the knife through its cutting stroke. 60
27. A machine for sewing shoes having, in combination, stitch-forming devices, a shoe supporting jack, a sewing cam shaft for operating said stitch-forming devices, mechanism for relatively actuating the stitch-forming devices and the jack to transfer the point of operation about the shoe, a thread cutting knife acting against the tread surface of the shoe to sever the thread, a power driven member, means normally disconnected 65

from said power driven member for projecting and retracting said knife, a clutch for coupling said normally disconnected means to sever the thread, and connections to the sewing cam shaft to effect coupling of the clutch upon the completion of the outseam.

28. An outsole shoe sewing machine having, in combination, a shoe clamping presser-foot, a work support beneath the presser-foot arranged to enter the crease between the upper and the sole, lockstitch forming devices acting to form a stitch with a shallow lock adjacent the tread surface of the shoe and a thread cutting knife mounted on the machine and movable to cut an incision 10 in the shoe and sever the thread below the lock while the shoe is retained between the presser-foot and work support.

29. An outsole shoe sewing machine having, in combination, stitch-forming devices, a shoe supporting jack, mechanism for relatively actuating the stitch-forming devices and the jack to transfer the point of operation about the shoe from within the area of the heel seat around the toe and back within the heel seat area, a thread 25 cutter for forming an incision in the tread surface of the shoe during thread cutting movement, and means for actuating the knife at a point within the area of the heel seat.

30. An outsole shoe sewing machine having, in combination, shoe supporting and guiding devices, comprising a work support and a presser-foot arranged to receive between them the projecting edge of the sole of a lasted shoe, lockstitch forming devices constructed and arranged 35 to sew the outseam of a shoe, and a knife edged member acting against the tread surface of the shoe to sever the thread between the presser-foot and work support.

31. An outsole shoe sewing machine having, in combination, stitch-forming devices, a shoe supporting jack, mechanism for relatively actuating the stitch-forming devices and the jack to transfer the point of operation about the shoe from within the area of the heel seat around the toe and back within the heel seat area, a thread 45 cutter acting against the tread surface of the shoe on the last completed stitch while the stitch-forming devices are in position to operate within the area of the heel seat, and means to operate 50 the thread cutter after the stitch-forming devices have been brought to rest at the end of a seam.

32. A machine for sewing shoes having, in combination, stitch-forming and work holding devices comprising a work table and a presser-foot mounted for oscillation about a fixed pivot point, a thread cutter movably supported on said presser-foot, an operating link extending from said thread cutter and provided with a pivotal connection centering about said presser-foot pivot point, and means for actuating said pivotal connection to one side of said pivot point.

33. An outsole shoe sewing machine having, in combination, stitch-forming devices, a work table and a presser-foot for retaining the shoe in operative relation to said stitch-forming devices, a thread cutter for severing the thread subsequently to the stopping of the stitching means, and a lever operatively connected to said thread cutter and 65 presser-foot for actuating them in succession to cut the thread and release the work.

34. An outsole shoe sewing machine having, in combination, stitch-forming devices, a work table and a presser-foot for retaining a lateral edge of 70 a shoe sole in operative relation to said stitch-

forming devices, a thread cutter for severing the thread, a driven member having connections to said thread cutter and presser foot arranged to actuate them in succession to cut the thread and release the shoe, and means for rendering the 5 driven member operative upon stopping the operation of the stitch-forming devices.

35. A shoe sewing machine having, in combination, stitch-forming devices, a thread tension, means operating to measure off a supply of thread 10 from the thread tension for each stitch, a thread cutter constructed and arranged to sever the thread close to the work upon completion of the seam, and while the work is retained in operative relation with the machine, and means for preventing the formation of a stitch of a seam subsequent to the last operation of the thread measuring means to provide a surplus of thread in the machine as the work is withdrawn from the stitch-forming devices. 20

36. A shoe sewing machine having, the combination, stitch-forming devices, a thread tension, means operating to measure off a surplus of thread from the thread tension at the end of a seam, a thread cutter constructed and arranged 25 to sever the thread close to the work upon completion of the seam, and mechanism acting to provide a further surplus of thread upon restarting the stitch-forming devices.

37. A shoe machine having, in combination, 30 stitching-forming devices, a shoe supporting jack, mechanism for relatively actuating the stitch-forming devices and the jack to transfer the point of operation about the shoe, automatically actuated and controlled mechanism for stopping 35 the stitch-forming devices at a predetermined point in the sewing operation, a thread cutter for severing the thread close to the work upon completion of the seam and while the work is retained in operative relation to the stitch-forming devices, means operating to measure off a 40 surplus of thread at the end of a seam and to provide a further surplus of thread upon restarting the stitch-forming devices and apparatus for initiating operation of said stitch-forming devices and for simultaneously operating said means to provide said further surplus.

38. A sewing machine having, in combination, stitch-forming devices including a work piercing needle, a thread take-up member, a thread tension 50 wheel, a work holding element having a needle clearance passage to support loosely the end of thread at the termination of the stitching operation and a connection to said tension wheel for rotating it a predetermined amount, measuring 55 off a supply of thread sufficient to avoid withdrawal of the thread from the passage in the work holding element when the thread is acted upon by said take-up member.

39. A sewing machine having, in combination, 60 stitch-forming devices, a thread tension wheel, means for starting the stitch-forming devices in operation, a ratchet connected to the tension wheel, a connection from said starting means to said ratchet for rotating the wheel in a direction to measure off a supply of thread upon operation of the starting means, and a shield adjustably arranged to cover a portion of said ratchet for determining the amount of thread to be measured. 70

40. A sewing machine having, in combination, stitch-forming devices, means operating during each cycle of operation of the stitch-forming devices to measure off a supply of thread lacking slightly the amount consumed during each cycle 75

of operation and a thread take-up member actuatable to set the stitch formed by said devices and simultaneously to draw an additional amount of thread needed to complete a stitch.

5 41. A sewing machine having, in combination, stitch-forming devices, a thread tension wheel, means operating during each cycle of operation of the stitch-forming devices to measure off from said tension wheel a supply of thread lacking 10 slightly the amount consumed during each cycle of operation and a thread take-up member actuatable to set the stitch formed by said devices and simultaneously to draw from said tension wheel the additional amount of thread needed to complete a stitch.

15 42. A sewing machine having, in combination, stitch-forming devices, a thread tension wheel, a brake acting on the tension wheel means operating during each stitch-forming cycle to release the 20 brake and to measure off from said tension wheel a supply of thread lacking slightly the amount consumed during each cycle of operation and a thread take-up member actuatable to set the stitch formed by said devices and simultaneously to draw an additional amount of thread 25 needed to complete a stitch against the action of said tension wheel while the brake is acting.

30 43. A sewing machine having, in combination, stitch-forming devices, a thread tension wheel, a brake acting on the tension wheel, means for measuring the thickness of the work, means connected to said measuring means and operating during each stitch-forming cycle to release the brake and to measure off from said tension wheel 35 a supply of thread lacking slightly the amount consumed during each cycle of operation and a thread take-up member adapted to set the stitch formed by said devices and simultaneously to draw an additional amount of thread needed to 40 complete the stitch, against the action of said tension wheel while the brake is acting.

44. A lockstitch sewing machine having, in combination with the other stitch-forming devices, a locking thread case, a rotary loop taker 45 for passing a loop of needle thread about the thread case, a thread lock for the locking thread mounted on the thread case against which the stitch is set, and a locking thread measuring member arranged to engage the thread between the 50 thread case and the work and draw thread from the thread case through the lock.

45. A lockstitch sewing machine having, in combination with the other stitch-forming devices, a locking thread case, a rotary loop taker 55 for passing a loop of needle thread about the thread case, a thread lock for the locking thread mounted on the thread case against which the stitch is set, a locking thread measuring member arranged to engage the thread between the thread 60 case and the work and draw thread from the thread case through the lock, and means on said loop taker for actuating the lock to release the thread in timed relation to the action of the thread measuring member.

65 46. A sewing machine having, in combination, lockstitch forming devices comprising a work piercing needle, a locking thread case, a rotary loop taker for passing a loop of needle thread 70 about the thread case, a locking thread holding member for supporting the locking thread adjacent the needle during its work piercing movement, and means for moving the locking thread holding member into engagement with the thread, 75 maintaining it in holding position during the

interval in which the needle engages the work and subsequently releasing the thread.

47. A sewing machine having, in combination, lockstitch forming devices comprising a work 5 piercing needle, a locking thread case, a rotary loop taker for passing a loop of needle thread about the thread case, a thread lock mounted on the thread case, and means on the loop taker to actuate the lock.

48. A sewing machine having, in combination, 10 lockstitch forming devices comprising a work piercing hook needle, a locking thread case, a rotary loop taker for passing a loop of needle thread about the thread case, a locking thread holding member for supporting the locking thread 15 between the thread case and the work, and means for moving the locking thread holding member into holding position before the needle engages the work and from holding position after a loop of thread has been passed about the thread case 20 by the loop taker.

49. A locking thread device for lockstitch sewing machines comprising a locking thread case having a thread lock, a bobbin reel within the case, a tension spring bearing on the reel, a 25 rotary loop taker arranged to pass a loop of needle thread about the locking thread case, and means on the loop taker to release the lock.

50. A locking thread device for lockstitch sewing machines comprising a locking thread case, 30 a thread lock on said case, a rotary loop taker arranged to pass a loop of needle thread about the locking thread case, and a roll mounted on a portion of the loop taker and arranged to move in a path occupied by the lock to operate the lock 35 at a predetermined point in the rotation of the loop taker.

51. A sewing machine having, in combination, lockstitch forming devices comprising a locking thread case, a needle thread loop taker for passing 40 a loop of thread about the case, a thread measuring member pivotally mounted to rotate about a central axis and provided with axially projecting measuring pins disposed with relation to the axis of rotation to draw off thread from 45 the bobbin while exerting substantially no backward strain on the length of thread between the measuring member and the work.

52. A lockstitch sewing machine having, in combination, stitch-forming devices comprising a 50 locking thread case, a rotary loop taker for passing a loop of needle thread about the locking thread case, a thread measuring member operable between the thread case and the work to measure a predetermined length of thread during 55 a part of each cycle of operation of the stitch-forming devices and to release the thread during the passage of the needle loop about the thread case and a shield for enclosing the thread measuring member during that part of the cycle of 60 operation in which the thread is released.

53. A sewing machine having, in combination, lockstitch forming devices comprising a work 65 piercing needle, a locking thread case, a rotary loop taker for passing a loop of needle thread about the thread case, a locking thread measuring member movable into and out of operative position with relation to a portion of the locking thread between the thread case and the work, and a shield for the thread measuring member 70 when moved to inoperative position.

54. A sewing machine having, in combination, lockstitch forming devices comprising a work 75 piercing hook needle, a locking thread case, a rotary loop taker, for passing a loop of needle thread

- about the thread case, a reciprocable thread measuring member movable into one position to grasp and measure a portion of locking thread and into another position to free the thread, and a shield for protecting the measuring member from entanglement with the needle thread subsequent to the actuation of the needle in presenting a loop of thread to the loop taker. 5
55. A sewing machine having, in combination, stitch-forming and work feeding devices including a needle, a work support and a presser-foot, means for actuating the work support and presser-foot to clamp and feed the work, means for actuating the needle to feed the work during the back feed of the work support and presser-foot, a work engaging knife arranged to move with the work while being fed by the needle, and connections from the needle actuating means for oscillating the knife in the line of feed to cut the work. 10
20. 56. A sewing machine having, in combination, stitch-forming and work feeding devices including a carrier, a work support and a presser-foot mounted on the carrier to clamp and feed the work, means for moving the carrier back and forth in the line of work feed, and a work engaging knife arranged to cut the work while clamped between the work support and presser-foot. 15
25. 57. A sewing machine having, in combination, stitch-forming and reciprocating work feeding devices reciprocating in the line of work feed, a work engaging knife mounted on one of said devices to cut the work independently of the reciprocating movement of said device, and means for adjusting simultaneously the operation of another of the work feeding devices and the cutting movement of the knife. 20
30. 58. A sewing machine having, in combination, a work piercing needle mounted for feeding movement, a cam actuated follower arm for operating the needle through its feeding movement, feeding connections between the needle and the cam arm including an adjustment for varying the length of feeding movement, a work engaging knife movable intermittently to cut the work and an operating member for said knife connected to said needle feeding connections, the point of attachment being located between said adjustment and the needle. 25
35. 59. A sewing machine having, in combination, a work piercing needle mounted for work feeding movement, means for operating the needle through its feeding movement and a work engaging knife laterally spaced from said needle and arranged to maintain substantially uniform displacement from said needle throughout the feeding movement thereof. 30
40. 60. An outsole shoe sewing machine having, in combination, lockstitch forming devices, a work support to guide the shoe in operative relation to the stitch-forming devices, a work gauge and a fudge knife, both movable with relation to the work support, and means for jointly operating said work gauge and fudge knife comprising concentrically mounted cams, an actuator for moving one of the cams, and an adjustable connection for operatively coupling said cams in fixed angular relation. 45
45. 61. An outsole shoe sewing machine having, in combination, lockstitch forming devices, a work support to guide the shoe in operative relation to the stitch-forming devices, a work gauge and a fudge knife, both movable with relation to the work support, and means for jointly operating said gauge and fudge knife comprising concentrically mounted cams, one for said gauge and one for said knife, a shaft carrying one of said cams, 50
50. a sleeve surrounding said shaft for rotating the other cam, an actuator for rotating said sleeve and an adjustable connection for holding the shaft in fixed angular relation to the sleeve. 55
55. 62. A sewing machine having, in combination, stitch-forming and work feeding devices including a work piercing needle, a work support and a work clamping presser-foot, mechanism for operating the presser-foot to release the work and for relatively reciprocating the needle laterally with respect to the work support and presser-foot along the line of feed to feed the work, and means for exerting a force in the direction of feed at the end of the needle as it projects beyond the work to stiffen the needle during a portion of its relative movement. 60
60. 63. A shoe sewing machine having, in combination, stitch-forming and work feeding devices including a curved hook needle movable laterally along the line of work feed, a work support and a work clamping presser-foot, and mechanism for operating the presser-foot to release the work and for relatively reciprocating the needle laterally with respect to the work support and presser-foot along the line of feed to feed the work, and means for exerting a force in the direction of feed at the end of the needle and toward the center of curvature of said needle as it projects beyond the work during its work feeding movement with respect to the work support and presser-foot. 65
65. 64. A shoe sewing machine having, in combination, stitch-forming and work feeding devices including a curved hook needle movable laterally along the line of work feed, a needle looper, a work support, and a work clamping presser-foot, and mechanism for operating the presser-foot to release the work and for relatively reciprocating the needle laterally with respect to the work support and presser-foot along the line of feed to feed the work, and for actuating the looper forwardly to lay the thread within the barb of the needle, then to the rear and in the direction of feed while the needle is moving with respect to the work support and presser-foot to feed the work. 70
70. 65. A sewing machine having, in combination, stitch-forming devices including a support, a stud provided with a screw thread engaging a screw threaded bearing in the support, needle and awl segments mounted on the stud, mechanism for oscillating the stud to produce feeding movements of the segments and means contained in the bearing for preventing lost motion between the stud and the oscillating mechanism. 75
75. 66. A sewing machine having, in combination, stitch-forming devices including a support, a stud provided with a screw thread, a screw threaded bearing on the support and surrounding the threaded end of the stud, needle and awl segments mounted on the stud, mechanism for oscillating the stud to produce feeding movements of the segments, a collar having an internal thread engaging the thread of the stud and an external thread engaging a corresponding thread on the bearing, the internal and external threads being formed with different pitches, and means for fixing the angular relation between the collar and the threaded bearing. 80
80. 67. A sewing machine having, in combination, a carrier mounted to reciprocate in the line of feed, a work support and a presser-foot on the carrier, a stud provided with a screw thread, a screw threaded bearing in the carrier, needle and awl segments mounted on the stud, mecha- 85

nism for reciprocating the carrier, mechanism for oscillating the stud, and means contained in the bearing for preventing lost motion between the stud and the oscillating mechanism.

5 68. A lockstitch sewing machine having, in combination, stitch-forming devices including a hook needle, an awl, a shuttle and a stitch setting take-up, means for causing the awl to enter the work after the needle withdraws with its 10 loop of thread from the work and before the stitch is set and a stop mechanism acting when thrown into operation and during a forward cycle of the stitch-forming devices to bring the machine to rest with the final stitch completed 15 and at a point in the cycle at which the awl is about to enter the work.

69. A lockstitch sewing machine having, in combination, stitch-forming devices including a hook needle, a needle looper, an awl, a shuttle 20 and a stitch setting take-up, means for causing the awl to enter the work after the needle withdraws with its loop of thread from the work and before the stitch is set, and a stop mechanism acting when thrown into operation to bring 25 the machine to rest and to cause the looper to misloop the needle.

70. A sewing machine having, in combination, devices for forming a lockstitch including a work piercing hook needle and a needle looper, a stop 30 mechanism for arresting the stitch-forming devices before completing the final stitch-forming cycle of movements, and a connection from said stop mechanism for causing said looper to misloop the needle during said final stitch forming 35 cycle.

71. A sewing machine having, in combination, stitch-forming devices for forming a lockstitch including a hook needle, a needle looper, and a shuttle, and a stop mechanism acting when 40 thrown into operation to bring the machine to rest and to cause the looper to misloop the needle during the final stitch-forming cycle of operation of the stitch forming devices.

72. A sewing machine having, in combination, 45 stitch-forming devices including a hook needle and a looper, a longitudinally and laterally movable looper carrying bar, an arm pivotally connected to the looper bar for moving the looper bar longitudinally, a carrier slidably arranged on 50 said looper bar for guiding the looper bar in its longitudinal movement, a support for said carrier comprising a plane surface along which the carrier is movable in any direction, and means for moving said carrier laterally in timed relation to the longitudinal movements of the looper 55 bar to cause the looper to traverse a path about the needle.

73. A sewing machine having, in combination, 60 stitch-forming devices including a hook needle and a looper, a longitudinally and laterally movable looper carrying bar, an arm pivotally connected to the looper bar for moving the looper bar longitudinally, a carrier slidably arranged on said looper bar for guiding the looper bar 65 in its longitudinal movement, an operating lever mounted for pivotal movement about a fixed center and pivotally connected at one end to the carrier for moving the carrier laterally of the looper bar to cause the looper to traverse a path 70 about the needle.

74. A sewing machine having, in combination, 75 stitch-forming devices including a hook needle and a looper, a cam shaft for operating the stitch-forming devices, a longitudinally and laterally movable looper carrying bar pivotally con-

nected to the looper bar, a cam operated arm pivotally connected to the looper bar for moving the looper bar longitudinally, a carrier slidably arranged on said looper bar for guiding the looper bar in its longitudinal movement, a support for said carrier comprising a plane surface along which the carrier is movable in any direction, an operating arm mounted for movement about a fixed center and pivotally connected at the one end to the carrier and a 10 follower actuated by the cam shaft for oscillating said carrier operating arm about the fixed center in timed relation to the movement of the arm connected to the looper bar to cause the looper to traverse a path about the needle. 15

75. A sewing machine having, in combination, stitch-forming devices including a hook needle and a looper, a cam shaft for operating the stitch-forming devices, a longitudinally and laterally movable looper carrying bar, a cam operated arm 20 pivotally connected to the looper bar for moving the looper bar longitudinally, a carrier slidably arranged on said looper bar for guiding the looper bar in its longitudinal movement, an operating arm mounted for movement about a fixed center 25 and pivotally connected at one end to the carrier, a follower actuated by the cam shaft for oscillating said carrier operating arm about the fixed center in timed relation to the movement of the arm connected to the looper bar to cause the 30 looper to traverse a path about the needle, and means for shifting the relative range of movement of one of said arms to prevent the laying of the thread within the barb of the needle.

76. A sewing machine having, in combination, 35 stitch-forming devices including a hook needle and a looper, a cam shaft for operating the stitch-forming devices, a longitudinally and laterally movable looper carrying bar, a cam operated arm pivotally connected to the looper bar for moving 40 the looper bar longitudinally, a carrier slidably arranged on said looper bar for guiding the looper bar in its longitudinal movement, an oscillating arm for moving the looper bar laterally, an operating lever pivotally connected to the carrier 45 and fulcrumed on the oscillating arm, said lever having one end movable into and out of the center about which said arm oscillates to shift the range of lateral movement of the looper bar carrier, a follower actuated by the cam shaft for actuating 50 said oscillating arm in timed relation to the movements of the arm connected to the looper bar to cause the looper to traverse a path about the needle, and means for shifting the end of the lever with respect to the center of oscillation of 55 the oscillating arm to prevent the laying of the thread within the barb of the needle.

77. A sewing machine having, in combination, 60 stitch-forming devices including a curved hook needle and a looper, a cam shaft for operating the 60 stitch-forming devices, a longitudinally and laterally movable looper carrying bar, a cam operated arm pivotally connected to the looper bar for moving the looper bar longitudinally, a carrier slidably arranged on said looper bar for guiding the 65 looper bar in its longitudinal movement, an oscillating arm for moving the looper bar laterally, an operating lever pivotally connected to the carrier and fulcrumed on the oscillating arm, a toggle, one member of which is connected to one end of 70 the lever and the other end of which is pivoted on the machine to hold, when in alinement, said end of the lever concentric with the center about which said arm oscillates, a follower actuated by the cam shaft for actuating said oscillating arm 75

in timed relation to the movements of the arm connected to the looper bar to cause the looper to traverse a path about the needle, and means for moving said toggle links into alinement upon initiating operation of the machine and out of alinement while the cam shaft is rotating just before stopping the machine to prevent the laying of thread within the barb of the needle.

78. A sewing machine having, in combination with other stitch forming devices, a work piercing needle, a locking thread case, a loop taker for passing a loop of needle thread about the thread case, a thread lock for preventing movement of the thread relative to the thread case in each stitch forming cycle while the stitch is being set, means for opening the thread lock in each cycle of the machine, and means operating to draw off a predetermined supply of thread through the open lock from the thread case after the stitch is set and while the stitch setting strain remains on the needle thread.

79. A sewing machine having, in combination with other stitch forming devices, a work piercing needle, a locking thread case, a loop taker for passing a loop of needle thread about the thread case, a thread lock for preventing movement of the thread relative to the thread case in each stitch forming cycle while the stitch is being set, means for opening the thread lock in each stitch forming cycle, and means operating to draw off a predetermined supply of thread from the thread case after the stitch is set and while the thread lock is open and to retain the supply while the needle thread loop is being taken from the needle.

80. A sewing machine having, in combination, lock-stitch sewing devices comprising a work piercing needle, a locking thread case constructed to support a bobbin reel, a rotary loop taker for passing a loop of needle thread about the thread case, a thread lock mounted on the thread case, a tension spring for the bobbin reel, and means on the loop taker to actuate the thread lock.

81. A sewing machine having, in combination, lock-stitch forming devices comprising a work piercing needle, a locking thread case, a rotary loop taker for passing a loop of needle thread about the thread case, a thread lock comprising gripping jaws mounted on the thread case between which the bobbin thread passes, and means for opening and closing the thread lock.

82. A sewing machine having, in combination, lock-stitch forming devices comprising a work piercing needle, a locking thread case, a thread lock comprising gripping jaws mounted on the thread case between which the bobbin thread passes, a spring acting to hold the jaws closed, and a cam on the loop taker acting to open the jaws against the force of the spring.

83. A sewing machine having, in combination with the other stitch forming devices, a work support, a presser foot, a needle, a take-up, a

locking thread case, a loop taker for passing a loop of needle thread about the thread case, a thread lock for preventing movement of the thread relative to the thread case in each stitch forming cycle while the stitch is being set, means operating to draw off a predetermined supply of locking thread from the thread case after each stitch is set, and a stopping mechanism arranged to bring the machine to rest after the operation of the thread measuring means and after the needle has withdrawn from the work during the cycle of the machine succeeding the completion of the last stitch.

84. A sewing machine having, in combination with the other stitch forming devices, a work support, a presser foot, a needle, a take-up, a locking thread case, a loop taker for passing a loop of needle thread about the thread case, a thread lock for preventing movement of the thread relative to the thread case in each stitch forming cycle while the stitch is being set, means operating to draw off a predetermined supply of locking thread from the thread case after each stitch is set, a thread cutting mechanism acting to sever the threads of the completed seam close to the work, and a stopping mechanism arranged to bring the machine to rest after the operation of the thread measuring means and after the needle has withdrawn from the work during the cycle of the machine succeeding the completion of the last stitch.

85. A lockstitch shoe sewing machine having, in combination with other stitch-forming devices, a work support, a presser-foot, a needle, a take-up, a locking thread case, a rotary loop taker for passing a loop of needle thread about the thread case, a thread cutter arranged to sever the threads of the completed seam while the work is retained between the work support and the presser-foot, and means operating to measure a supply of thread from the thread case before the thread cutter acts, and to hold the measured supply while the thread cutter severs the threads.

86. An outsole shoe sewing machine having, in combination with the other stitch forming devices, a work support, a presser-foot, a needle, a take-up, a locking thread case, a loop taker for passing a loop of needle thread about the thread case, means operating to draw off a supply of locking thread from the thread case sufficient to insure its engagement by the needle loop during the formation of the first stitch of the next seam, a thread cutting mechanism acting upon stopping the machine and after the operation of said thread drawing means to sever the threads of the completed seam close to the work while the work is retained between the work support and the presser-foot, and a stopping mechanism acting when thrown into operation to bring the machine to rest.

OTTO R. HAAS.
